UNITED STATES PATENT OFFICE.

JOHN G. ROBERTS, OF CHICAGO, ILLINOIS, ASSIGNOR, BY MESNE ASSIGNMENTS, TO
WESTERN ELECTRIC COMPANY, INCORPORATED, A CORPORATION OF NEW YORK.

AUTOMATIC TELEPHONE EXCHANGE.

Application filed March 10, 1906. Serial No. 305,272.

To all whom it may concern:

Be it known that I, JOHN G. ROBERTS, a citizen of the United States, residing at Chicago, in the county of Cook and State of Illinois, have invented certain new and useful Improvements in Automatic Telephone Exchanges, of which the following is a specification.

My invention relates to a system of circuits and apparatus designed for use in a telephone exchange system wherein the operation of connecting the lines for telephonic communication is performed through the medium of mechanism operating automatically. More especially, my invention relates to a "full" automatic system wherein the automatic mechanism is controlled by apparatus located at the subscribers' stations. It is, however, to be understood that various features of my invention may be applied advantageously in systems of types differing specifically from the one herein described. The principal object of my invention is to provide a system employing automatic switching apparatus or mechanism which in its operation will embody the desirable features of the best manual switching systems and will operate in an efficient manner.

With this main object in view I have devised circuits and apparatus, and have combined them in a complete automatic telephone exchange organization capable of accommodating and providing for the interconnection of an almost unlimited number of telephone lines, which may be either party lines,—that is, lines each of which is connected with and serves a plurality of subscribers' stations or independent lines,—that is, lines each of which serves but a single subscriber's station and wherein the several stations on a line may have their call signals or bells selectively actuated from the central office, and may control the mechanisms at the central office involved in establishing connection with other lines, and in transmitting the various signals incident to such interconnection, without requiring the provision of the customary earth connection or common return conductor, or having recourse to the use of more than two conductors between the substation, or group of substations, and the central office.

In the system of my invention I so or-

ganize the substation controlling mechanism and the central office selectors that a series of the selectors, such as a group selector and a line connector, operate in succession in response to current variations or impulses over a subscriber's line circuit. This circuit comprises only the two conductors, such as the ordinary metallic circuit wires, which, upon the connection being established, form the metallic circuit conductors for telephonic communication. The current variations controlled from the subscribers' stations and transmitted over the metallic line circuit occur in successive periods and the selector or connector mechanisms at the central office operate one after another during such successive periods. At the end of each period which marks also the beginning of the next succeeding period, a current variation occurs which determines the extent of movement of one selector switch and transfers the control to the next succeeding mechanism. These operations take place under the control of a single line circuit, and I am thus enabled to dispense entirely with the ground connections at the subscribers' stations.

The mechanism selectively operated serves, upon the initiation of a call at any one of the substations, to prevent any intrusion upon the calling line on the part of any other line by disconnecting the circuit through which connection is completed to the calling line, and at the same time establishing a peculiar electrical condition on the terminals of the line through which connection with it is completed, thus indicating that the line is engaged. It serves to find, in succession, trunks that are not in use extending through the groups of ten thousands, thousands, hundreds and tens to the particular line with which the calling line is to be connected, and, having selected the line, it serves to test its free or busy condition. If the selected line is engaged, the mechanism responds to the peculiar electrical condition existing upon its terminals, and transmits a tone or other distinctive signal to the calling subscriber to indicate that the called line is busy; if the line is not engaged, the mechanism is actuated through the agency of the controlling device at the calling substation to select the ringing current to which the station wanted is adapted.

to respond, and to apply this particular current to the line. It serves, after the ringing current has been applied to the called line a certain number of times without any response from the called substation, automatically to disconnect the ringing current, and to apply a tone or a characteristic signal to the calling line to indicate that the called subscriber does not answer. If, on the other hand, the subscriber responds to the calling signal, the mechanism operates automatically to disconnect the ringing current from the line, and to complete the communication circuit between the called and the calling lines; and, finally, it serves, upon the hanging up of the telephone of the calling substation at the end of the conversation, to bring about an automatic restoration of the normal condition of the connecting and selecting circuits and apparatus.

To effect the selective actuation of the central office mechanism through the medium of a single circuit extending between the substation and the central office, and having no earth connection at the substation, I provide a circuit controlling device at the substation which is adapted to modify the flow of current in the circuit, and produce a series of impulses, each impulse having a certain predetermined duration. The length or duration of any of the impulses may be varied by varying the relation to each other of parts of the controlling device provided for that purpose; and the duration of each impulse determines the operation of a certain part of the automatic mechanism at the central office. The organization of this mechanism is such that each impulse of current in the circuit controls the movement of one of the switches concerned in the selecting of the called line and its interconnection with the calling line, and the extent of movement of each switch is dependent upon the duration of the particular current impulse to which it is adapted to respond. This result I attain by associating with each switch a constantly and uniformly moving part, which is brought into operative relation with the movable member of the switch at the beginning of the current impulse, and which remains in operative relation with it until the impulse ends, the switch member being held in the position to which it has been advanced by suitable electrically controlled retaining mechanism.

In connection with the switches that are selectively responsive to the duration of the impulses, I provide other switches which, so to speak, distribute the impulses of the series each to its corresponding selecting switch, the distributing switch being selectively responsive to the number of impulses, and not to their duration. I prefer to arrange these distributing, or controlling, switches so that each will respond to certain

consecutive impulses in the series, and not to the others, the switches having a step-by-step movement, one step for each of the impulses to which they are responsive, and being retained in the position to which they are advanced in the last step by suitable electrically controlled mechanism.

I am thus enabled, by providing a controlling device at the substation adapted to produce in the circuit of the line a certain number of impulses of current, each impulse having a certain predetermined duration variable at will, to effect any desired selective actuation of the series of electrically operated switches at the central office which are involved in the selection of the called line, its interconnection with the calling line, and in the transmission to both the calling and the called lines of the appropriate signals.

In carrying my invention into effect, I have provided a number of new and advantageous features, among which, in addition to the method of selectively actuating the central office mechanism through the medium of a single circuit by means of impulses of current having certain peculiar characteristics of number and duration, may be mentioned the substation interrupter or controlling device by means of which these impulses are produced and their characteristics determined; the arrangement for selectively operating the selecting switches by means of constantly moving electrically controlled mechanism; the organization of selecting switches and distributing, or controlling, switches in two selectively actuated and cooperating series; the arrangement whereby automatic means is operated upon a connection being made with a multi-station line for selectively signaling the desired station thereon; the arrangement whereby the ringing current for signalling a particular substation of a party line is selected through the agency of mechanism under the control of the calling subscriber; the arrangement whereby the selected ringing current is brought into connection with the called line and automatically applied for a predetermined number of times; the organization which operates automatically to disconnect the ringing current from the line and to notify the calling subscriber of the non-response of the called subscriber at the end of the predetermined time; the organization for automatically withdrawing the ringing current and completing the circuit between the called and the calling lines upon the response of the called subscriber; and a number of other features having to do with the organization of the circuits and apparatus which will be more particularly described hereinafter.

I will describe my invention in connection with the accompanying drawings, wherein

Figs. 1, 2, 3 and 4 taken together constitute a diagrammatic representation of the circuit which is involved in establishing connection between a calling and a called subscriber's line in an automatic telephone exchange equipped in accordance with my invention, and designed to accommodate up to one hundred thousand lines; Fig. 5, a front elevation, partially in section on line 5—5 10 of Fig. 7, of the substation interrupter or circuit controlling device; Fig. 6, a sectional view of the same on lines 6—6 of Figs. 5 and 7; Fig. 7 an end elevation of the interrupter partially broken away and in section on lines 7—7 of Figs. 5 and 6; Fig. 8, a front elevation of the outside of the interrupter with part of the enclosing shell broken away; Figs. 9, 10, and 11, detail views of parts of the interrupter; Fig. 12, a 15 front elevation of one of the selecting switches arranged for actuation by magnetically-controlled constantly-moving mechanism; Fig. 13 a side elevation of the same; Fig. 14, an elevation of one of the controlling or distributing switches; Fig. 15, a sectional plan view of the same; and Fig. 16, a detail view of one set of the connection terminals of the switch.

I shall first describe the mechanism concerned in the production of the current impulses in the circuit of the line and the determination of the duration or length of each impulse. This mechanism I have designed with the particular object of meeting the requirements of a system operating in accordance with my invention; but it will be understood that devices for determining the number and duration of current impulses might be produced in a great variety 35 of forms, and for this reason I wish it to be understood that I do not limit my invention to its employment with the particular mechanism herein described.

The substation interrupter, or controlling device, which I find it convenient in the present instance to employ, is illustrated in Figs. 5 through 11, and is designated by the reference character G. It comprises essentially a switch g, or circuit controlling device, with mechanism for causing it to open and close its contacts a predetermined number of times, and to vary at will the length of time between interruptions. The switch and its controlling mechanism are supported on a frame consisting, in the present instance, of the base g⁵¹ from which project the partitions or flanges g⁵⁰ and g⁵², over which an enclosing shell g⁵⁰ is placed to enclose and protect the mechanism mounted within. The frame and shell may be metal, or of any suitable material. The switch g comprises a stationary part or anvil and a movable switch spring which normally rests upon the anvil, the spring having a projecting portion which is adapted to be en-

gaged by an adjusting screw g² carried on the end of a bell crank lever g¹ pivoted to the flange g⁵² of the frame on which the switch is mounted, the other end of the bell crank lever carrying a part g³, preferably 70 in the form of a roller, which is adapted to be engaged by a disk g⁴ having a periphery provided with alternate elevations and depressions, so that as the disk is rotated the lever g¹ is oscillated to alternately open 75 and close the contacts of the switch g. The disk g⁴ is carried upon the end of an elongated ratchet wheel g⁵ journaled at its ends in the flanges g⁴⁹ and g⁵² of the frame. The ratchet with its associated disk, whose alternate elevations and depressions correspond with the teeth of the ratchet, is turned step by step by a series of actuating members distributed along the length of the ratchet, and each adapted to cause the advance of the 80 ratchet through one step. These actuating parts, in the present instance, are eleven in number, and are designated g¹⁵, g¹⁷, g¹⁹, g²¹, g²², g²⁴, g²⁶, g²⁷, g²⁸, g³⁰, and g³¹. The general construction of the actuating parts is 85 plainly shown in Fig. 11. Each part is, in the present instance, in the form of an arm journaled at one end upon a sleeve g³², which extends between the flanges of the frame approximately along the center of the device, 90 and at the other end carries a downwardly projecting segmental horn g⁵⁶ provided with a spring finger g⁶ adapted to engage a tooth of the ratchet g⁵ to advance it, (the flexibility of the spring finger keeping it from 95 interfering with the advance of the ratchet by the other actuating members), and with a shoulder g⁵⁸ which is designed to engage a stop bar g⁵⁴ extending transversely across the frame, to limit the downward movement of the actuating part and prevent it from advancing the ratchet wheel more than 100 one step. Each arm also carries a ratchet portion, preferably extending upward from the arm on the arc of a circle concentric 105 with the shaft or sleeve upon which the arm is journaled, and having as many teeth as may be required. In the present instance, g¹⁹, g²¹, g²⁴, g²⁷ and g³⁰ are each provided with ten teeth as shown in Fig. 11, g¹⁷ with four 110 teeth, g²², g²⁶ and g²⁸ each with but one tooth, while g¹⁵, the last member in the series, has no teeth, each arm also bears a pawl g⁷, preferably on the side of the arm away from the ratchet, adapted to engage and co-operate with the teeth of the ratchet carried on the adjoining arm. Between certain of the actuating arms shielding members of the character illustrated in Fig. 10 are interposed. Each of these members comprises an 115 arm fulcrumed at one end of the sleeve g³², upon which the actuating members are fulcrumed, and provided at the other end with a portion g⁸ adapted to be interposed between the pawl of one actuating member and 120

the ratchet portion of the next actuating member in the series. This shielding portion g^8 may conveniently be formed, as shown, by bending the arm laterally at right angles to its plane, the forward portion of the arm being again bent forwardly into a plane parallel with that of the rear portion of the arm and carrying a segmental enlargement g^{11} , provided with a knurled edge 10 adapted to project through a corresponding slot in the plate g^{57} in the front of the interrupter. Projecting laterally from the segment g^{11} of the shielding member is a portion g^{10} on an arc having its center in the axis of the sleeve on which the member is journaled, and provided on its lower portion with numerals or suitable characters brought into view one at a time through a corresponding aperture in the front plate g^{57} to indicate the extent of displacement of the arm about its shaft, and on the upper portion with corrugations corresponding in number and separation with the number and separation of the characters on the lower part of the lateral projection, and designed to co-operate with a retaining finger g^{12} to hold the shielding arm in any position to which it may be moved by means of its projecting knurled edge. Each shielding arm is also provided with a part adapted to engage the stop bar g^{54} to limit the downward movement of the arm. Mounted upon the shaft or sleeve g^{32} adjacent to each of the actuating arms, and secured to the sleeve so as not to be rotatable thereon, is a collar g^{34} which serves as an abutment for a spiral spring g^{33} the other end of which is secured to the actuating arm, and which serves to return the arm to its normal resting position against the stop bar g^{54} after it has been displaced therefrom. No retracting springs are provided for the shielding members, which are adapted to remain in the position to which they are manually moved.

In the arrangement as described the operation of the switch g is effected by the return of the actuating members to their normal resting positions, one after the other, after having been displaced therefrom. To provide for their displacement, and their return to normal position at a uniform and invariable rate of speed, I provide the following mechanism: Through the hollow shaft or sleeve g^{32} there extends a shaft g^{35} , which terminates at one end in a screw-threaded portion upon which is a nut g^{38} extending over the end of the sleeve g^{32} to prevent the longitudinal displacement of the shaft in the sleeve, and at the other end is provided with an enlarged portion or head pinned to an extension shaft g^{60} , which is journaled in the flange g^{49} of the frame, and to the end of which a handle g^{88} is secured. The hub of the first actuating arm, g^{16} , of the series is rigidly secured to the enlarged portion of

the shaft to rotate therewith, while the hubs of the other actuating and shielding arms are, as has heretofore been stated, loosely mounted on the sleeve g^{32} so as to be capable of rotation thereon. The sleeve g^{32} is supported at one end by a screw-threaded portion of reduced diameter which passes through the flange g^{52} and is secured thereto by means of a nut, as shown, and at the other end by its engagement with the enlarged end of the shaft g^{35} , which is rotatable within it. To provide for the restoration of the shaft and its associated parts after they have been turned from their normal position by means of the handle g^{88} , I employ, in the present instance, a spiral spring g^{39} one end of which is suitably secured to the enlarged end of the extension shaft g^{60} , while the other end is made fast to an abutment g^{70} mounted upon the frame; and in order that the restoration of the shaft from its displaced to its normal position may be at a uniform and invariable rate of speed, I employ a heavy balance wheel g^{44} and escapement mechanism comprising an escapement g^{45} suitably fulcrumed, and connected with the balance wheel by means of a spring g^{47} secured to an abutment g^{46} on the wheel, together with an escapement wheel g^{43} journaled upon the extension shaft g^{60} . By means of a ratchet wheel g^{42} rigidly secured to the escapement wheel, and adapted to be engaged by a pawl g^{41} carried on an arm g^{40} rigidly secured to the extension shaft g^{60} , I bring about the result that the movement of the shaft g^{35} is under the control of the escapement mechanism only in the return movement of the shaft, the pawl on arm g^{40} acting to couple the arm with the escapement wheel only in the return movement of the arm. The balance wheel is made of such relatively large mass, and the spring which connects it with the escapement is so proportioned that the movement of the escapement wheel, and the shaft which it controls, is slow and at a practically uniform rate of speed. The balance wheel, as shown, is journaled between a bridging support g^{45} and the flange g^{49} of the frame.

As has been stated, the hub of the actuating arm g^{16} , the first in the series, is rigidly secured to the shaft g^{35} , and it is through this arm that movement is imparted to the other arms in the series in the operation of the device. When the handle g^{88} is turned to cause the rotation of the shaft, the arm g^{16} is caused to rotate, and the pawl g^7 carried at the end of the arm is brought into engagement with one of the teeth of the ratchet portion of the next actuating arm in the series, the tooth engaged depending on to what extent the shield of the intervening shielding member of arm g^{16} is interposed between the pawl and the ratchet with which it co-operates. As soon as the pawl

of g^{15} and the ratchet of g^{17} engage, the movement of the shaft is imparted to g^{17} which, in turn, causes its pawl to come into engagement with the ratchet of the succeeding actuating member, and so on down the line. It will be obvious that the extent to which any one of the actuating members will be moved before movement is imparted to the next member or arm in the series will depend entirely upon the extent of interposition of the shield of the intervening shielding member between the pawl of one and the ratchet of the other; and that therefore the interval of time which will elapse between the return to its normal position of one actuating member and the return to its normal position of the preceding actuating member of the series in the return movement of the mechanism, and hence the interval between actuations of the switch g , may be predetermined by moving the intervening shielding member through any predetermined arc.

It will be noted that certain of the actuating members, namely, g^{22} , g^{25} , g^{28} , and g^{31} , are provided with only one tooth with which the pawl of the preceding member of the series can engage, and that no shielding member is interposed between either of them and the preceding actuating member. This is because the operation of the automatic mechanism which the device under description controls does not require at these points in the sequence of impulses an impulse of variable duration, and therefore it is sufficient to provide for a current impulse of any certain fixed duration by employing but one tooth, and locating it so as to insure a fixed and constant movement of the preceding member before movement is imparted to this member. The function of the shields at the points in the series where they are located is, so to speak, merely to provide means for effacing or rendering inoperative all of the teeth but the first one with which engagement is permitted, and, by being made movable in their relation to the teeth of the associated ratchet, to make the position of the operative tooth variable at will.

When, in the use of the interrupter described above, a call is to be made for a particular line in the exchange, the position of each of the shielding arms is adjusted by means of its knurled edge, which projects through the corresponding slot in the face plate of the device, so as to cause the numbers or characters which appear at the apertures in the face plate, reading from left to right, to correspond with the number of the station with which connection is desired. When this is done, each shield is so interposed between its associated members as to produce certain time intervals between the starting of their respective movements when the handle is turned to set the device, and between the ending of their movements when the members are allowed to return to their normal positions. Actuating member g^{15} is the first to be moved from its resting position, and member g^{31} the last; and in the return movement g^{31} is the first to return to its home position and g^{15} the last, each member in succession as it returns to its home position turning the ratchet g^5 one step, and, through the medium of the disk g^4 and the lever g^1 , causing the switch g to open and close its circuit. This succession of makes and breaks in the circuit which the switch g controls following each other at predetermined intervals, varying according to the operative relation of the actuating members to each other, effects the selective actuation of the central office mechanism in a manner hereinafter to be described. The shields, it will be observed, remain in the positions in which they are set, thus enabling the call to be repeated without the necessity of again setting up the number; while the actuating members are moved back to their normal positions each by means of its associated spring g^{33} which has been put under tension in the setting movement of the handle, the return movement of the shaft merely serving through the medium of the interconnected series of members to retard their return movement and regulate the same to a constant and uniform speed.

I will now describe the switch which I have designed to respond selectively to the duration of the current impulses determined by the substation interrupting mechanism, such as that just described. One form of switch which I find it convenient to employ, is illustrated in Figs. 12 and 13. So far as the switch mechanism proper is concerned it does not differ greatly from that employed in a well known automatic telephone exchange system, and which is illustrated and described in Patent No. 638,249, issued December 5, 1899 to Keith and Erickson, the principal feature of difference being in the organization which I have provided for effecting and controlling the movement of the movable switch members. The switch comprises, in the present instance, a frame consisting of two parallel rods k^{16} and transverse plates k^{17} upon which are mounted the movable and stationary switch contact members and the mechanism for operating them. The movable members k^1 , k^2 , k^3 , and k^4 are rigidly secured to a rod k , from which they are insulated by insulating sleeves k^{30} . Associated with each of the movable member k^1 , k^2 , and k^3 are a number of stationary contact members k^{18} , which may be arranged in banks of ten rows, fourteen contacts in a row, or in any other grouping which the character of the circuits which are to be controlled

6 requires. As shown, the lower movable contact member k^4 is arranged to engage but a single contact piece k^5 .

7 As is customary in a switch of this character, the movable members are adapted to be brought into contact with any one of the fixed or stationary contact members by two movements, one vertical, and the other horizontal, the vertical movement being first 10 caused to bring the movable member opposite a particular row of contacts with one of which the connection is to be made, and the rotary movement causing the arm to sweep over the contacts in that row 15 until it completes connection with the one desired. It has been customary to effect this movement of the movable members of the switch by means of two electro magnets operating through the medium of step-by-step mechanism, one to raise the shaft or rod k step by step the desired distance, and the other to rotate it step by step until the desired fixed contact is engaged. In accordance with my invention I employ, instead of 20 this step-by-step mechanism, constantly moving parts magnetically moved into engagement with a part associated with the rod k to effect the vertical movement and the horizontal movement of the rod. The 25 driven part, or part associated with the rod, is shown in the present instance as a cylinder k^{24} which is adapted to be engaged by two constantly rotating disks k^{23} and k^8 , the first mentioned disk being adapted, 30 when it is moved into contact with the driven cylinder k^{23} to cause the shaft or rod k with its associated switch members to move up, while the disk k^8 , when moved into contact with the driven cylinder, is 35 adapted to impart to the rod and its associated switch arms a movement of rotation. The disks k^{23} and k^8 are similarly arranged, both being fulcrumed in the end of levers k^{22} , k^7 respectively, and both being 40 in engagement with constantly rotating disks k^{25} , k^{26} , respectively, carried upon shafts k^{27} , k^{28} , respectively, which are constantly and uniformly driven by any suitable source of power. The levers k^{22} , k^7 , 45 respectively, are fulcrumed upon, or concentric with, their associated shafts k^{27} and k^{28} , and each carries, in the present instance on the end opposite the end which carries the disk, an armature which is in operative 50 relation with electro-magnets k^{21} and k^6 , respectively, suitably mounted upon the frame of the switch. The magnet k^6 also serves, in the present instance, to actuate 55 through the medium of its armature a switch k^1 , with which a roller k^{12} , or like part carried upon the end of the armature, is adapted to be brought into engagement 60 when the magnet is energized. In order to effect the appropriate movement of the movable switch members, the mechanism ac-

tuated by a magnet k^{21} is mounted so that disk k^{23} rotates in a vertical plane just out of contact with the driven cylinder k^{24} ; while the mechanism actuated by magnet k^6 is so arranged that the disk k^8 rotates in 70 a horizontal plane just out of contact with the driven cylinder. The driving disks are normally held in their retracted positions by any suitable means.

With the rod or shaft k of the switch I 75 associate a retracting spring k^{20} , which serves to return the switch members to their normal resting position; and, to prevent such return excepting at the proper time, I 80 provide magnetically controlled retaining mechanism, comprising a vertical retaining ratchet k^{14} , a horizontal retaining ratchet k^{15} , and a magnet k^9 , the armature k^{10} of which co-operates with two pawls k^{11} and k^{29} , the first of which is adapted to engage 85 the teeth of the horizontal retaining ratchet k^{15} , and the latter the teeth of the vertical retaining ratchet k^{14} when the magnet is energized. Upon the de-energization of the magnet 90 the armature operates upon the pawls k^{11} and k^{29} to cause them to release their associated ratchets, whereupon the shaft k with its movable switch members is free to return to its normal position. The vertical retaining ratchet k^{14} is made in the 95 form of a cylinder around the circumference of which the teeth extend, so that the pawl which engages the teeth does not prevent the rotation of the shaft k after it has been raised the required distance; and likewise the horizontal retaining ratchet k^{15} is in the 100 form of a cylinder with the teeth extending longitudinally thereof, to permit the vertical movement of the shaft while preventing its horizontal rotary movement. 105

In the operation of the switch, an impulse of current is caused to pass through magnet k^{21} , which responds by attracting its armature and bringing disk k^{23} into contact with the driven cylinder k^{24} . As the disk is 110 constantly rotated, it immediately causes an upward movement of the cylinder, and, as the speed of rotation is maintained uniform at all times, the extent of the upward movement is exactly determined by the length of time during which the impulse of current passes through the magnet. When the current ceases the constantly rotating disk k^{23} is immediately withdrawn from the cylinder, and the shaft is held in the position to 115 which it has been moved by the engagement of retaining pawl k^{29} with the ratchet k^{14} . The operation of the controlling mechanism thereupon causes an impulse of current to 120 traverse the coils of magnet k^6 which, responding, moves the constantly rotating disk k^8 into contact with the driven cylinder and thus imparts to the shaft k and its associated switch members a movement of rotation. This movement takes place at a uniform 125

rate, and ceases immediately upon the cessation of the current flow in the magnet k^6 , the extent of movement thus depending upon the duration of the current impulse. The shaft is held in the position to which it has been rotated by the engagement of pawl k^{11} with ratchet k^{15} , and the switch held at the point to which it has been advanced, as long as current, which was imparted to magnet k^6 before the operation of magnets k^{21} and k^6 , continues to flow through retaining magnet k^6 . When this current ceases, the pawls release the ratchets and the switch parts return to their normal positions. It will be observed that movable contact arm k^4 remains in engagement with its associated contact part k^6 during the vertical upward movement of the shaft, and is withdrawn therefrom at the outset of the movement of rotation of the arm.

In Figs. 14, 15 and 16 is illustrated another form of switch which I find it convenient to employ in the circuit of my invention. This switch does not differ greatly from types well known in the art, and does not require extended description. It comprises a frame h^{17} arranged to be secured to any suitable support, and upon which the parts of the device are mounted. The movable contact members of the switch h^1 , h^2 , h^8 and h^4 are mounted upon, but insulated from, a rod or shaft h fulcrumed in the support, and provided with a spring h^{20} for returning it to its normal position when it is moved therefrom. Each movable switch member co-operates with a series of stationary or fixed contact terminals h^{18} , being adapted to complete connection with one after the other of the contacts as it is swung about by the rotation of the rod. Movement is imparted to the rod and the associated switch members by means of an electromagnet h^6 through the medium of a pawl h^8 carried upon the armature h^7 of the magnet, and co-operating with a ratchet h^{15} mounted, in the present instance, upon the upper part of the rod. The switch arms are maintained in the position to which they have been moved by means of a retaining pawl h^{11} normally held away from the ratchet h^{15} by the engagement therewith of the armature h^{10} of another magnet h^6 , the retaining pawl being allowed to come in contact with the ratchet when the magnet h^6 is energized to attract its armature. To render the mechanism incapable of advancing the movable switch members beyond the last stationary terminal each is adapted to engage, and hence irresponsible to all but a predetermined number of the current impulses that traverse the magnet h^6 , I provide the ratchet wheel h^{15} with only as many teeth each for the advancing pawl and the retaining pawl as correspond with the advanced positions which the movable mem-

bers are adapted to occupy. Any further actuation of the magnet h^6 is thus ineffective to cause a further advance of the switch arms. The magnet h^6 is also arranged to operate a switch h^{13} the members of which are suitably mounted upon but insulated from the frame, the arrangement being such that the switch maintains its contacts open so long as the armature is retracted, and closes them when the magnet is energized. The switch shown associated with the magnet h^6 , in the present instance, comprises only two contact members; but any other number and combination of contact members may be substituted as the circuit or circuits to be controlled require. Likewise, although the present switch is illustrated as being provided with four movable contact members each adapted to co-operate with four fixed or stationary contact terminals, it will be understood that any other combination of movable and fixed members may be provided as desired.

I shall now describe the circuits by means of which the mechanism described in the foregoing, together with other apparatus which is well known and requires no detailed description, is combined in an organization through which the novel operation which is the object of my invention is attained. The circuit organization is illustrated diagrammatically in Figs. 1, 2, 3 and 4 of the drawings, which illustrate two telephone lines, each provided with a plurality of substations, together with the series of circuits which would be required to link them together for conversation assuming that they were in an automatic telephone exchange adapted to serve up to one hundred thousand lines. The various controlling and interconnecting switches are diagrammatically indicated, and will be recognized as being similar to or of the type of the switches described in the foregoing portion of the specification. For the sake of simplicity in illustration, many parts of the mechanism which are not essential to the understanding of the circuit connections are omitted, including all excepting part of one horizontal row of stationary contacts in each bank of the switches adapted for both vertical and horizontal movement; and for the same reason a number of batteries and earth connections are shown at different points in the figures, whereas it will be understood that these batteries might be, and in most cases would be, one and the same battery adapted to supply current for the operation of the entire system, while the connections illustrated as being to earth might be to a single common return conductor.

The scheme for effecting interconnection between any two lines in the exchange which is followed in the present instance may be briefly stated as follows: Each subscriber's

line is terminated upon the movable members of a switch which are adapted in one position to extend the line to a co-operating switch through the medium of which any particular line may be selected in case of a call outgoing from the line in question, and which are adapted in another position to connect the line with stationary contact terminals of other switches through which connection is completed with the line in case of a call incoming to it. The movable contact terminals of the co-operating switch associated with each line are adapted to complete connection with any trunk which is not busy of a number terminating upon the stationary or fixed terminals of the switch. This trunk extends to the movable terminals of another automatic switch which may have ten rows of fixed terminals, representing the ten groups of ten thousand lines each into which the exchange may be divided, and as many contacts in each row as there are trunk lines extending from this switch to the group of ten thousand. By causing the movable contacts of the switch to move vertically a predetermined distance, any particular group of ten thousand may be selected, and, in the horizontal movement of the switch which follows, any of the trunks extending to this group which is not busy is appropriated. The trunk thus found terminates at its other end upon the movable contacts of a switch whose ten rows represent the ten groups of one thousand lines each into which the lines of the larger group are divided, while the contacts in each row represent the number of trunks extending from this switch to the particular thousand lines represented by the row. The predetermined vertical movement of the movable members of this switch selects the particular thousand group desired, and the horizontal movement finds a trunk which is not busy and completes connection with it. The other end of the trunk found terminates upon the movable members of a switch whose ten rows of fixed contacts represent ten groups of a hundred each into which the group of one thousand lines is divided, and whose contacts in each row represent the trunks extending to this particular hundred. In like manner, the vertical movement of the movable members of the switch selects the particular hundred desired, while the horizontal movement finds a free trunk extending to this hundred and makes connection therewith. The other end of the trunk thus selected extends to the movable members of the switch which serves to complete connection with the particular line called, the ten rows of contacts representing the ten groups of ten into which the hundred is divided, and the ten contacts in each row being connected with the ten individual lines which that row represents. The verti-

cal movement of the movable member selects the proper ten's group, and the horizontal movement selects and completes connection with the line desired.

I have designated the four substations of the calling line A^1 , A^2 , A^3 and A^4 , and the four substations of the called line, A^5 , A^6 , A^7 , and A^8 . Each substation is provided with the usual telephonic apparatus, comprising in the present instance the call bell a , a condenser a^1 , an induction coil a^2 , a transmitter a^3 , telephone receiver a^4 and a switch hook a^5 ; and in addition there is provided at each substation an interrupter or circuit controller G of the type hereinbefore described, or of any form which will perform the work of this interrupter. The telephone line extends from the four substations A^1 , A^2 , A^3 and A^4 in two limbs 1 and 2 to the movable terminals of a controlling switch H at the central office B , while the telephone line which serves substations A^5 , A^6 , A^7 and A^8 extends in two limbs 23 and 24 to the movable terminals of controlling switch H^1 at the central office designated F . An extension of the telephone line 1, 2 connects with the fixed or stationary contact terminals of a number of connecting switches U^1 , subject, however, to the control of switch H , while the limbs 23, 24 of the other telephone line extend to the fixed contact terminals of a number of connecting switches U , U^2 , subject to the control of switch H^1 . Each line entering the exchange has, in the present instance, a normal connection with the poles of a central battery V , one of the limbs of the line including the magnet which serves to actuate the controlling switch on the movable members of which the line terminates. To avoid confusion, this arrangement is not illustrated in the case of the line extending from substations A^5 , A^6 , A^7 , and A^8 to the central office; but in the case of the line extending from substations A^1 , A^2 , A^3 and A^4 , the magnet h^6 is shown included between limb 2 of the line and the free pole of the battery V . To provide a return path for the current which flows to the line through magnet h^6 , and at the same time to balance the line against inductive disturbances, an inductance or retardation coil b is connected between the limb 1 of the line and the other or grounded pole of the battery.

The switch H , as shown, is provided with four movable contact arms h^1 , h^2 , h^3 , and h^4 , mounted on but insulated from the shaft h the rotation of which is controlled by the magnet h^6 ; and, as shown, each arm is adapted normally to rest on one and to be brought into contact with three other stationary contact terminals. The first two stationary contacts of each series engaged by contact arms h^1 and h^2 of the switch are connected with conductors 25 and 26 ex-

tending to the stationary contact terminals which represent the line terminating on switch H on the various connecting switches U¹. In their third position the arms h¹, h² 5 rest on dead or disconnected terminals, and in their fourth position extend the circuit of the conductors 1 and 2 of the line to conductors 3 and 4 which are connected with contact arms i¹ and i² of the associated 10 finder switch I. The arm h³, which is connected to earth, or the earthed pole of the battery, completes no circuit in its normal or resting position, but in its second, third and fourth positions grounds conductor 27, 15 which is connected on switches U¹ to the stationary terminals associated with conductors 25 and 26, and which serves as a test conductor to indicate, by its changed electrical condition when the switch H is operated, that the line 1, 2 is engaged. The arm h⁴ of the switch is connected with the free pole of the central battery V and completes no circuit either in its first, or normal, or 20 in its second position; but in its third and 25 fourth positions closes a conductor 28 which extends through the actuating magnet i⁸ of the associated finder switch I, and thence to earth or the other pole of the battery by way of the resting contact of arm i⁴ of that 30 switch, and which also has a branch 29 extending to earth through the winding of the retaining magnet i⁹ of the switch I.

The winding of retaining magnet h⁹ is included in a conductor 33 extending between 35 the poles of the battery, and controlled in contacts h¹⁸ of the actuating magnet h⁸ of the switch, the circuit being closed to energize the retaining magnet to allow the pawl h¹¹ to engage the ratchet h¹⁵ when current 40 flows through the winding of magnet h⁸. It is necessary that the pawl h¹¹ shall be in engagement with the ratchet to retain the switch in its advanced position while the armature h⁷ of magnet h⁸ is being moved 45 back and forth by the impulses in the line circuit to advance the switch; and in order that the pawl may not be released during the brief intervals when the armature h⁷ is unattracted, and conductor 33 therefore 50 opened at contact h¹⁸, I preferably make the magnet h⁹ sluggish in its action by shunting its winding with a resistance h¹² which serves to take the discharge of the magnet and cause current to continue to circulate 55 in the local circuit during the momentary interruption of conductor 33. Any interruption of the circuit longer than the momentary one which occurs as the armature of magnet h⁸ moves back and forth in causing the step-by-step advance of the switch arms, permits the de-energization of magnet h⁸, thus making the retaining pawl inoperative and permitting the switch to return 60 to its normal position. It will be understood that this result may be obtained, and

the relatively sluggish operation of retaining pawl h¹¹ be effected in a number of other ways well known in the art.

Referring now more particularly to the 70 finder switch I, which is associated with controlling switch H and is individual to the line 1, 2 extending to substations A¹, A², A³ and A⁴, this switch is structurally practically the same as the switch illustrated in 75 Figs. 12 and 13 of the drawings and hereinbefore described, excepting that it has but a single row of stationary contacts for each movable switch arm, and therefore is enabled to dispense with the mechanism for effecting a vertical movement of the switch 80 arms. This switch has four arms i¹, i², i³ and i⁴, the first two and the last of which, as has been previously stated, are connected to conductors 3 and 4 and to earth, respectively, while arm i³ is normally connected by way of conductor 30 to earth through the resting contacts of the switch i¹³ operated by the actuating magnet of the switch I, and, in the alternative position of the switch, to the portion of conductor 28 extending between the actuating magnet i⁸ and the resting contact of arm i⁴. The fixed terminals, with which arms, i¹, i² and i³ are adapted to come into engagement as they are rotated, are connected with the conductors of 85 a number of trunk lines, the two line conductors 5, 6 of each trunk being terminated upon corresponding contacts of the series with which arms i¹ and i² co-operate, while the local or test conductor 31 associated with 90 each trunk is terminated upon a corresponding contact of the series which arm i³ is adapted to engage. In the drawing but a single trunk 5, 6 is illustrated, with its conductors 5, 6 and 31 connected to other like 95 finder switches I, but it will be understood that the other stationary contacts, of which there may be any desired number, of the switch I are all likewise connected to other trunks. 100

In the operation of the controlling switch H and the finder switch I described above, the closure of the telephone switch at any one of the four substations connected with line 1, 2 closes a circuit whereby current may flow steadily out through actuating magnet h⁸ of switch H and back through the retardation coil b. This causes the actuating magnet to attract its armature and advance 115 all of the arms of switch H one step, from their first or normal to their second position, which, it will be seen, does not interrupt the circuit normally existing between line 1, 2 and conductors 25, 26 extending to the connecting switches U¹, but merely 120 serves to cause arm h³ to connect conductor 27 to earth to make line 1, 2 "busy" to other lines. The first of the succession of current 125 impulses determined in the line by the operation of interrupter G at the substation 130

advances all of the arms of switch H to their third position and thereby disconnects conductors 25, 26 from the line, but does not affect the connection which has been established between conductor 27 and earth. The first impulse of the series also, in advancing arm h^4 to its third position, closes the circuit of conductor 28 and thereby brings about the energization of magnet i^3 of the 5 finder switch I to allow the retaining pawl to engage the ratchet; and also causes actuating magnet i^8 to attract its armature and thus bring the constantly rotating disk i^8 into contact with the driven disk i^{24} of the 10 switch. The shaft i of switch I thereupon starts to rotate, causing the contact arms to sweep over the fixed contact members upon which the various trunks 5, 6 terminate. In the first stage of the movement of 15 the switch arms, arm i^4 breaks the earth connection of conductor 28 in which the winding of actuating magnet i^8 is included; but the actuating magnet, in moving the 20 rotating disk i^8 into contact with the driven disk to cause the rotation of the switch, also operates switch i^{18} causing the switch spring to open its normal and close its alternative contact, which completes a circuit for 25 actuating magnet i^8 through conductor 30 to the arm i^8 of the switch. This arm in the movement of the switch is swept over the contacts upon which the local or test conductors 31 of the various trunks terminate, and as, as will hereinafter be described, these conductors are grounded when 30 the trunks with which they are associated are busy, the actuating circuit for magnet i^8 will be completed and the rotation of the switch arms will continue so long as the 35 arm i^8 is moving over terminals representing trunks that are busy. But as soon as it passes onto the contact of a trunk which is free, it finds no circuit for the current flowing through actuating magnet i^8 , and 40 that magnet is de-energized and permits the constantly rotating disk i^8 to be disengaged from the driven disk, the switch arms being maintained in the position to which they have been moved by retaining pawl 45 i^{11} . As soon as the actuating magnet is de-energized, the spring of switch i^{18} returns to its normal resting contact and thereby applies a ground to conductor 30, thus grounding the test contacts of the trunk 50 with which connection has been made at all the switches to which the trunk is multipled, and preventing the trunk from being appropriated by any other switch. The second impulse of current determined by the 55 substation interrupter now occurs, and advances all of the arms of switch H to their fourth and last position, causing arms h^1 and h^2 to extend the circuit of line 1, 2 to conductors 3, 4, which have just been connected to trunk conductors 5, 6 by switch I.

The advance of arms h^3 and h^4 to their fourth position does not effect any change in the circuits which they control, the conductor 27 remaining grounded to keep the "busy" test condition on the associated terminals of the switches U^1 and the circuit of conductor 28 remaining grounded to maintain energized the retaining magnet of switch I, thus holding the switch arms in the position to which they have been moved. Subsequent impulses determined by interrupter G and transmitted over the circuit, do not cause any further change in the position of switch H on account of the mechanical inability of the actuating magnet to advance the ratchet mechanism more than three steps.

The trunk line 5, 6 with which the line 1, 2 is connected at B through the medium of the switches H and I, extends to another group comprising a controlling switch J and a finder switch K located at the point in the sequence marked C. The controlling switch J of this group is structurally identical with the controlling switch H described above, excepting that it has an extra set of contacts h^{14} controlled by the armature of the actuating magnet. Inasmuch as the other parts of the switch correspond in all respects with like parts of switch H, I have designated them by the same reference characters.

The construction of the finder switch K is illustrated in Figs. 12 and 13, and has been hereinbefore described; it differs from finder switch I in employing banks of stationary contacts to be engaged by each switch arm, instead of single rows, and vertical movement mechanism for enabling the arms to be brought into engagement with any row in a bank. In all respects other than those noted the construction of controlling switch J and finder switch K is similar to the construction of controlling switch H and finder switch I. However, owing to its location at a point in the circuit scheme where it would probably be necessary to extend the line to connecting apparatus at a distant office, as it is from this point that ten groups of trunks extending to ten groups of ten thousand subscribers' lines each ramify, it may be desirable to provide a greater number of contacts in the horizontal rows of switch K to accommodate a greater number of trunks in each group, so that greater flexibility of connection may be attained, and thus, on the whole, fewer trunks be required to serve the entire exchange. The conductors 5, 6 of the trunk line terminate upon arms h^1 , h^2 of the switch J but are made discontinuous with respect to direct or steady currents flowing over the line by having condensers c^1 , c^2 interposed in them. The actuating magnet h^8 of the controlling switch is connected in an extension 130

of conductor 6 to the free pole of the battery V, the extension connecting with the conductor at a point between the condenser c^2 and the end of the line to which the calling substation is connected, so that it may be responsive to the impulses of current determined by the substation interrupter G. In order that the impulses may be relayed to the actuating magnets of the switches 5 beyond this switch in the series, I provide a bridge 34 of the line between the condensers and the movable members h^1 , h^2 of switch J, and control this bridge in the normally open contacts h^{14} of the switch operated by the actuating magnet h^6 ; to prevent the shunting of voice currents across this bridge, I include therein a retardation coil c.

The stationary terminals with which the 20 movable arms h^1 , h^2 of the switch J are adapted to engage, are, as shown, four in number; but inasmuch as no circuit is completed by the arms until they have reached their fourth position, it will be obvious that 25 all excepting the fourth contacts in the series might be dispensed with, so far as these two arms are concerned. The fourth contacts in the series are connected with conductors 7 and 8, respectively, which extend to arms k^1 , k^2 of the finder switch K associated with controlling switch J. The movable arm h^3 of the controlling switch is arranged to control a normally open circuit 35 which includes the retaining magnet k^9 of finder switch K, the circuit being arranged to be maintained closed in the last three positions occupied by the arm h^8 . Inasmuch as no change in the circuit conditions takes place while the arm h^8 is moving 40 through its second, third and fourth positions, it is obvious that the same result might be accomplished by dispensing with the third and fourth stationary contacts, and so arranging the switch arm that it would 45 remain on the second contact while the other arms were advancing to their third and fourth positions; or by arranging the arm to slide on a single contact which would extend over the space occupied by the three 50 contacts. This may also be said of other parts of the mechanism of the various switches where no change of circuit is brought about during certain stages in the movement of the switch arms.

55 Arm h^4 is connected by way of conductor 36 with the free pole of the battery V, and is adapted in its second position to close the circuit of the vertical actuating magnet k^{21} of the finder switch K by way of conductor 37; to open this circuit and complete one by way of conductor 38 through the horizontal actuating magnet k^8 in its third position; and in its final position to open the last mentioned circuit. The horizontal actuating magnet of finder switch K, as is

the case in finder switch I, has its actuating circuit completed in a normally closed contact of the movable arm k^4 of the switch, the circuit through this path being opened at the outset of the rotary movement of 70 the switch, and an alternative circuit being provided by way of conductor 39 to switch arm k^8 through the operation of the switch k^{13} controlled by the armature of the horizontal actuating magnet k^6 , the continued actuation of the magnet k^6 depending upon the "busy" condition of the trunks over the terminals of which arm k^8 sweeps in the movement of the switch. As was described in connection with switch I, when 75 the arm k^8 moves into contact with the terminal of an idle trunk it finds no circuit for the current flowing through the horizontal actuating magnet k^6 , which, becoming inert, stops the rotary movement of the switch arms, and at the same time, by permitting switch k^{13} to resume its normal position, places an earth connection on the test terminal of the trunk with which connection is made by way of conductor 40 80 multiplied to all of the switches with which this trunk is connected, and thus prevents intrusion.

The operation of the switches J and K is substantially the same as that described in 85 connection with switches H and I. The first impulse of current which reaches the actuating magnet h^6 of switch J is that which effected the last step of the movement of switch H. This impulse moves the arms of switch J to their second position, and in so doing closes the circuit 35 of retaining magnet k^9 of switch K and also closes the circuit of vertical actuating magnet k^{21} . The vertical movement of the arms k^1 , k^2 , k^3 and k^4 90 thereupon commences, and continues as long as arm h^4 of switch J remains in its second position, which is determined by the duration of the current impulse. The next impulse of current, by opening the circuit of the vertical actuating magnet, ends the vertical movement and closes the circuit 38 of horizontal actuating magnet k^8 , which remains closed until an idle trunk has been found, as heretofore described. This current impulse, as in the case of switch I and the other finder switches, is of sufficient duration to enable the arms to sweep over all of the stationary contacts in the row, in case it is necessary, and upon the next impulse the arms of switch J move to their 95 fourth and final position, completing connection between the trunk line 5, 6 and the conductors 7, 8 which have just been extended to the trunk 9, 10.

The circuit is illustrated as extending from the switches J and K at C by way of trunk line 9, 10 to a controlling switch L and a finder switch M at D, thence by way of trunk 13, 14 to a group comprising a con- 100 105 110 115 120 125 130

trolling switch N and finder switch O at E, and finally by way of trunk 17, 18 to the connecting and signaling apparatus at F. The construction and operation of the switches L and M at D are exactly similar to the construction and operation of the switches J and K at C, excepting that, as the trunk line 9, 10 is not made discontinuous at this point by the interposition of condensers, it is unnecessary to provide switch contacts and a circuit for relaying the impulses, which contacts are therefore omitted from controlling switch L; while a retardation coil d is connected with limb 9 of the trunk to furnish a return path for the current which flows through the actuating magnet of the controlling switch. The construction of the switches and the circuit arrangement at E is similar to that 20 at D, excepting that no retardation coil is connected with the line, the coil d associated with controlling switch L at D also furnishing a return for the current which flows through the actuating magnet of controlling switch N.

The trunk 17, 18 selected by the switch at E extends to the movable arms p^1 , p^2 of the controlling switch P at F, and includes in its limbs condensers f^1 , f^2 to render it 30 continuous to direct or steady currents flowing over the line. The controlling switch P in its construction and relation to the circuits which it controls is generally similar to the controlling switches heretofore described. In its construction it differs from them primarily in being provided with an additional actuating magnet p^{21} and an additional switch arm p^5 , and in being arranged to be advanced five steps instead of 40 four. It comprises five switch arms p^1 , p^2 , p^3 , p^4 and p^5 adapted to be advanced by means of actuating magnet p^6 acting on ratchet p^{15} through the medium of armature p^7 and pawl p^8 , and to be moved the 45 final step in the advance by means of a second actuating magnet p^{21} also acting on the ratchet through the medium of a pawl p^{28} . I have found it convenient to employ the actuating magnet p^{21} in addition to magnet 50 p^6 , although the arrangement may be such that the final step in the advance is effected through the medium of actuating magnet p^6 . The switch arms are held in the position to which they are moved by means of retaining pawl p^{11} controlled by retaining magnet p^9 through the medium of armature p^{10} , the winding of the retaining magnet being shunted by the resistance p^{12} . Two switches 55 p^{13} and p^{14} are provided, and arranged to be actuated by the armature of the actuating magnet p^6 . The arms p^1 , and p^2 of the switch govern the extension of the limbs of the trunk line 17, 18; the arm p^5 controls a selecting and connecting switch U, a ringing current selecting switch S, and an auto-

matic ringing key T, all associated with the controlling switch and involved in the completion of connection with the called line; the arm p^4 controls the retaining magnets of the switches U and S; and the arm p^3 assists in the control of a circuit which determines the connection with the line of the tone producing apparatus R.

The tone producing apparatus R comprises, in the present instance, a suitable 75 source of current r^3 , having a circuit 58 completed through the winding and contacts r^2 of a relay r^1 , and including one winding of an induction coil or transformer r , the other winding of which extends to a 80 relay Q by means of which the tone may be applied to the line. The tone is produced by the making and breaking of the circuit 58 in the contacts of relay r^1 , which produces by induction a rapidly alternating 85 current flow in the other winding of the transformer r . The application of the tone to the line through the medium of relay Q is effected by mounting this relay in inductive 90 relation to the actuating magnet p^6 of the switch P so that when the relay Q is actuated, under the conditions hereinafter to be described, the varying current induced in the secondary of transformer r will flow through the winding of relay Q, and thus 95 induce a varying current in the winding of actuating magnet p^6 , which is connected with the limb 18 of the line.

The connecting and selecting switch U corresponds structurally with the finder 100 switches K, M and O previously described, excepting that it omits one of the movable switch arms, being provided with three instead of four, and also omits the switch k^{12} controlled by the armature of the horizontal 105 actuating magnet. This is because the circuit through its horizontal actuating magnet is not automatically controlled by the condition of the lines over which the terminals of one of the switch arms 110 passes, but is under the sole control of the current impulses, and moves to and makes contact with a predetermined one of the fixed terminals in the row, whether the line associated with that terminal is 115 busy or not. The selecting and connecting switch comprises the three movable arms u^1 , u^2 and u^3 each adapted, as in the case of the other switches of this type heretofore described, to co-operate with ten rows of fixed 120 or stationary terminals, there being in the case of the present switch ten contacts in each row. The arms are moved through the medium of the driven disk u^{24} with which the vertical movement disk u^{23} and the horizontal movement disk u^8 are adapted to be brought into engagement when their respective armatures u^{21} and u^6 are attracted by the magnets u^{21} and u^6 , respectively. The 125 switches are maintained in the position to 130

which they have been moved by the vertical and horizontal retaining pawls controlled by the retaining magnet u^9 through the medium of its armature u^{10} .

5 The ringing current selecting switch S is generally similar to the finder switch I. It has a single contact arm s^1 arranged to be swung over four stationary contact terminals, the arm having no vertical movement. The advance of the arm s^1 is effected through the agency of a disk s^8 in engagement with a constantly rotating disk s^{24} , and adapted to be brought into engagement with the driven disk s^{24} of the switch 10 through the agency of the actuating magnet s^8 . The arm is held in the position to which it is moved by means of a retaining pawl s^{11} controlled by the armature s^{10} of retaining magnet s^9 . The four fixed 15 terminals with which the arm is adapted to be brought into engagement are connected through the medium of conductors 65, 66, 67 and 68 with four suitable sources of ringing current, as, for instance, the commutators of a generator W adapted to deliver alternating currents of a different periodicity from each commutator.

20 The construction of the switch T for controlling the application to the called line of the ringing current selected by switch S will, it is believed, be sufficiently clear from the diagrammatic representation which is shown. It comprises a disk t rotatably mounted and having about its periphery a 25 number of projections t^2 which are adapted in succession to engage and actuate the ringing switch, comprising the springs t^4 , t^5 each moving between resting and alternate contacts, and also, at a certain stage in the operation of the disk, being adapted to actuate another switch t^3 , consisting of a spring normally out of engagement with its co-operating contact. The rotation of the disk is effected by means of a constantly driven 30 disk t^8 carried on an armature t^6 controlled by the actuating magnet t^9 , a spring t^1 serving to retract the disk to its normal position when it is released by the driving disk t^8 . It is obvious that other methods may be 35 employed for controlling the actuation of the ringing key, the mechanism described in the present instance being merely illustrative of the scheme of operation.

40 The circuits for the above described mechanism are as follows: The energizing circuit for the actuating magnet p^6 of the switch P extends from the free pole of the central battery through the winding of the magnet to the limb 18 of the trunk line and thence over conductors 18, 16, 14, 12, 10 and 8 through the various switches which control these conductors back to the contacts h^{14} of the controlling switch J at C, the return circuit being through bridging conductor 34 and retardation coil c to the other

45 pole of the battery through conductors 7 and 9 and retardation coil d associated with controlling switch L. The energizing circuit 50 for the retaining magnet p^9 of this switch is controlled in contacts p^{13} of the switch, as in the case of the other controlling switches, and also passes through the normally closed contacts q^1 of the tone controlling switch Q, to the free pole of the battery V. A branch 60 of conductor 55 55 extends to the arm p^5 of the switch, where it is adapted to be connected successively with conductors 61, 62, 63 and 64 extending to the grounded pole of the central battery through the vertical movement magnet u^{21} of selecting and connecting switch U, the horizontal movement magnet u^6 of this switch, the actuating magnet s^6 of ringing current selecting switch S, and the actuating magnet t^6 of automatic ringing switch T, respectively. Another branch 53 of conductors 59 and 60 60 extends to the portion of conductor 18 connected with arm p^2 of the switch P, and includes the winding of magnet P^{21} , thus placing the magnet under the control of switch P^{13} . The arm p^4 of controlling switch P is connected with the free pole of the central battery, and is adapted when moved from its normal position to complete a circuit 65 65 extending through the retaining magnets s^9 and u^6 of switches S and U, respectively. Arm p^8 of the switch is connected by means of conductor 55 to the arm u^8 of the connecting switch U by means of which it is adapted to be brought successively into contact with the third or test conductors 56 of the various 70 telephone lines connected with the stationary terminals of this switch. The stationary contact which arm p^8 is adapted to engage in its fourth position, is connected through the medium of conductor 54 to the free pole of the battery V by way of the winding q^3 of tone controlling relay Q and switch p^{14} of actuating magnet p^6 . The stationary contacts which the arm p^8 engages in its last 75 two positions are connected to earth, so that the conductor 56 of the line upon which arm u^8 rests when connection is completed is grounded and thus caused to test "busy."

80 The arms p^1 and p^2 , as previously stated, are connected through the medium of condensers f^1 , f^2 , with limbs 17 and 18 of the trunk line extending from the switch at E, and are adapted in their final position to extend the trunk line to conductors 19 and 20, which are connected to the arms u^1 , u^2 of switch U through the normal or resting contacts of the switch t^6 of automatic ringing key T. The spring t^4 of this switch which is connected with arm u^1 , is adapted in its alternative position to complete connection with the arm s^1 of switch S by way of conductor 69, and thus apply to arm u^1 , and thus to limb 21 of the called line, ringing 85 90 95 100 105 110 115 120 125 130

current of the character determined by the position which arm s^1 occupies. Spring t^3 of the ringing switch, which is connected with arm u^2 , is adapted in its alternative position to connect the arm, and through its limb 22 of the called line, to earth or the common return conductor through a resistance t^9 . The switch t^3 associated with the automatic ringing key T controls a branch to ground of circuit 54 which includes the magnet of tone switch Q, and is adapted to be actuated to complete this branch after the ringing switch has been operated to apply ringing current to the called line a predetermined number of times,—illustrated in the present instance as three times, although this may be varied as desired.

The various switches and mechanisms located at F co-operate as follows: Upon the first impulse of current relayed over the trunk line 17, 18 by switch h^{14} of controlling switch J, the arms of switch P are advanced one step, arm p^4 completing the circuit of retaining magnets s^9 and u^9 of switches S and U, respectively, and arm p^5 starting the vertical movement of the selecting and connecting switch U through the medium of magnet u^{21} . Upon the next impulse, and the consequent advance of the arms of switch P to their third position, the vertical movement of the arm of switch U is stopped by the interruption of circuit 61, and the horizontal movement commenced by the completion of circuit 62 through magnet u^8 , the circuit of the retaining magnets s^9 and u^9 remaining closed through this and the subsequent advance of the switch arms. Upon the next impulse, and the advancement of the switch arms to their fourth position, the horizontal movement of the arms of switch U is stopped by the interruption of circuit 62, and the arm s^1 of switch S started to select the particular ringing current to be applied to the line by the completion of circuit 63 through the magnet s^6 . At the same time arm p^8 completes the circuit 54 of the tone controlling relay Q to arm u^8 of switch U, and, if conductor 56 connected with the stationary terminal upon which arm u^8 rests is grounded, causes the energization of the tone relay to apply the tone to the calling line to indicate that the called line is busy, and also to open the circuits of conductors 59 and 60 to permit the de-energization of retaining magnet p^9 and the withdrawal of actuating current from arm p^6 . If conductor 56 is not grounded, indicating that the called line is free for connection, the next impulse of current advances the arms of switch P to their fifth position thus interrupting circuit 63 and stopping the movement of switch arm s^1 of the ringing current selecting switch, and at the same time closing circuit 64 of the actuating magnet of automatic ringing key T, and completing

connection between conductors 17, 18 and 55 and 19, 20 and ground respectively. The ringing key T thereupon operates to apply the ringing current selected by switch S to the called line. During this operation the called line is alternately connected with the source of ringing current and with actuating magnet p^{21} of the switch P through the medium of conductors 20 and 53, so that when the circuit of the line is closed by the response of the called subscriber magnet p^{21} 75 attracts its armature and causes the advance of the switch arms P to their sixth or final position, thus opening the circuit 64 of the actuating magnet of ringing key T. 80

If the actuating magnet p^{21} is not energized to cause the switch arms to advance to their final position, the disk of ringing key T rotates until one of the projections on its periphery causes the closure of circuit 54 85 of the tone controlling relay Q in the contacts of switch t^3 , whereupon relay Q is actuated to apply the tone to the calling line in the manner hereinbefore described, and, by opening circuit 59 in its contacts q^1 permits the armature of retaining magnet p^9 to fall back and release the pawl p^{11} . 90

The operation of the entire system may be summarized as follows: Assume that the subscriber at station A¹ associated with telephone line 1, 2 desires to obtain connection with station A⁷ of line 23, 24, which we will assume is station No. 3 on line No. 56832. He will first set his substation interrupter G so that the numerals 56832 3 appear in the openings in the face plate of the device, reading from left to right. By doing this he so relates the adjustable actuating members of the interrupter to each other that the switch q will be actuated, when the handle of the device is turned as far as it will go and then released, to produce impulses in the line circuit having durations as follows:

Impulse.	Duration.	110
1st	Sufficient for switch I to swing over horizontal terminals.	
2nd	Five units.	
3rd	Sufficient for switch K to swing over horizontal terminals.	115
4th	Six units.	
5th	Sufficient for switch M to swing over horizontal terminals.	
6th	Eight units.	
7th	Sufficient for switch O to swing over horizontal terminals.	120
8th	Three units.	
9th	Two units.	
10th	Three units.	

Having set the interrupter he removes his telephone from the hook, thus closing the circuit of the line through the telephone apparatus and energizing actuating magnet h^6 of switch H to cause the advance of its 125

arms to their second position, which causes the line to test "busy", by grounding test conductor 27, but does not interrupt its connection with conductors 25 and 26 incoming from the connecting switch U'. He then turns the handle of the interrupter G as far as it will go and releases it, thus causing the actuating members to return to their home positions one by one and operate switch g to interrupt the circuit of the line in the predetermined sequence, and produce impulses of the predetermined duration. At the outset of the first impulse the arms of switch H are advanced to their third position, disconnecting the line from incoming conductors 25 and 26, and starting the movement of finder switch I. The arms of this switch rotate until the circuit of the actuating magnet z^3 is opened by arm z^3 passing on to the terminal of a trunk line 5, 6 which is not engaged, when the movement of the arms is automatically stopped, as heretofore described. At the end of an interval sufficient to allow the arms of the finder switch I to traverse all of the stationary contact terminals if necessary, the first impulse is terminated, and upon the occurrence of the second impulse the arms of switch H are advanced to their final position, thus extending the circuit of the line through conductors 3 and 4 to the conductors 5, 6 of the trunk upon which the arms of switch I have stopped. This immediately completes the circuit through the actuating magnet of switch J at point C which advances its arms to their second position, and starts the vertical movement of switch K, this movement continuing during the five units of time to which the second impulse is limited. Upon the termination of the second impulse the vertical movement of switch K stops, and upon the third impulse, which immediately follows, the arms of switch J are advanced to their third position whereupon the horizontal movement of the arms of switch K commences, this movement stopping automatically when an unengaged trunk line has been found, and before the termination of the impulse. Upon the passage of the fourth impulse the arms of switch J are advanced to their final position, extending the circuit of the line on by way of conductors 7 and 8 to the trunk 9, 10 which has been found by switch K, and, by the closure of the bridge 34 of the line in the switch contacts h^{14} of controlling switch J, causing the energization of the actuating magnet of controlling switch L to advance its contact arms to their second position, thus closing the circuit of the vertical movement magnet of switch M. The vertical movement of this switch continues during the continuance of the fourth impulse, which has been noted as being equal to six units, and the switch arms have there-

fore been raised to the sixth row of contacts when the termination of the fourth and commencement of the fifth impulse cause the switch L to advance its arms to their third position and thus stop the vertical movement and start the horizontal movement of the switch M. This movement continues until an unengaged trunk is found, when it is automatically stopped, and, upon the occurrence of the sixth impulse, switch L advances its contact arms to their final position and extends the line on by way of conductors 11 and 12 to the selected trunk 13, 14, and starts the vertical movement of switch O through the agency of controlling switch N. The duration of the seventh impulse being eight units of time, the switch arms of switch O have been raised to the eighth row of stationary contacts when the vertical movement is stopped; and upon the occurrence of the seventh impulse the horizontal movement of switch O commences and continues until a free trunk is found, after which the eighth impulse advances the switch N to its final position and continues the circuit of the line by way of conductors 15 and 16 to conductors 17 and 18 of the selected trunk. The passage of the eighth impulse through the magnet of switch P causes the switch to move its arms to their second position, and thus starts the vertical movement of the connecting switch U, which is stopped at the end of three units of time leaving the arms opposite the third row of contacts. The ninth impulse advances the arms of switch P to their third position and starts the horizontal movement of the arms of switch U, which continues for the predetermined two units of time, at the end of which the tenth impulse causes them to come to rest upon the second terminal of the third row of each of the banks of contacts which they engage. The arms of the switch P are at the same time advanced to their fourth position, whereupon the arm of ringing current selecting switch S starts to move and continues during the three units of time which elapse until the termination of the tenth impulse, coming to rest at the end of the impulse on the third contact, which is connected with the commutator of the ringing current generator W adapted to produce current of the character required for actuating the third station A' of the line with which the connection is made.

The closure of the circuit which follows the termination of the tenth impulse advances the arms of switch P to their fifth position, and starts the automatic ringing key T, which causes the application of the ringing current selected to the called line for a predetermined number of times, as hereinbefore described, thus ringing the bell at substation A'. When the subscriber re-

sponds by removing his telephone from the hook, the closure of the circuit causes actuating magnet p^{21} of switch P to advance the arms of the switch to their final position, 5 thus stopping the application of ringing current to the called line, and leaving the two lines connected for conversation. When the conversation is ended, the calling subscriber, by replacing his telephone on its hook, causes an interruption of the line circuit of sufficient duration to permit the armature of actuating magnet h^6 of switch H to fall back and open the circuit of retaining magnet h^9 , which allows the arms of the 10 switch to turn back to their normal position, again rendering the line available for incoming connections over conductors 25 and 26, and taking the busy test off of conductor 27. The restoration of the arms 15 of switch H to their normal position interrupts the circuit of the retaining magnet of the switch I, which returns to its normal position, and opens the circuit 5, 6 over which connection has been established 20 between the calling and called subscribers' lines. The opening of this circuit acts, by permitting the release of the retaining pawls 25 of the switches all along the line, to cause all of the switches to return to their normal 25 positions.

If, instead of being free, the called line is busy when the arms of switch U complete connection with it, the presence of a ground connection on the test conductors 56 associated with the line completes the circuit of the tone controlling relay Q through conductor 54, arm p^8 of the switch P, conductor 55 and arm u^8 of the switch U, causing it to attract its 30 armature and apply the tone from the generating apparatus R to the calling line by the inductive action between magnet q^8 of switch Q and magnet p^8 of switch P, as heretofore described; the application of the tone 35 continuing until the locking circuit through the magnet and contacts q^2 and relay Q has been interrupted by the opening of switch p^{14} , which occurs when the calling subscriber hangs up his telephone.

If the called line is free, but the subscriber does not answer the call, after the ringing current has been applied for a predetermined number of times, three in the present instance, the circuit 54 of the tone relay Q is completed by the branch extending through contacts t^8 of the automatic ringing key T. This causes the application of the tone signal to the calling line in the same manner as when the called line is busy, the calling subscriber recognizing this as a "don't answer" 50 signal on account of the greater time which elapses after the call before the signal is heard.

It will be observed that the connection of arm p^8 with the central battery is controlled 55

in contacts p^{18} of the actuating magnet p^6 of the switch; this is in order that the arm may be disconnected from battery during its return to its normal position after the switch has been released, so that momentary impulses of current may not be caused to flow to the various magnets in the circuit connected with the contacts which the arm p^5 traverses.

To the end that the description of my invention may be as concise as possible consistent with a full disclosure thereof, I have refrained from showing and describing minutely such parts as are well known in and may be supplied from the art. It will be understood that not only may the number and the voltage of the various sources of current, and the resistances to which the various actuating magnets are wound, be suited to the conditions which arise in practice, but, so far as the broad features of novelty are concerned, the character of the apparatus and the circuits employed to carry the invention into effect may be varied within wide limits without departing from the scope and spirit of my invention. Moreover in the system of my invention there are utilized a number of novel features which are capable of being advantageously employed in other systems, and are therefore not to be restricted to the particular system described and illustrated.

I do not here separately claim the substation controlling device that governs the sequence and duration of the impulses transmitted over the line and thus determines the operation of the automatic switches at the central office, this feature having been made the subject matter of my Patent No. 875,951, dated January 7, 1908.

I claim:

1. In an automatic telephone exchange, the combination with a plurality of substations and lines extending thereto from a central office, of a circuit through which connection is adapted to be made to one of said lines from the others, another circuit through which connection is adapted to be made from said line to the others, a busy test conductor associated with said line, an electro-magnetic switch adapted to close the busy test conductor in the first stage of its movement, to disconnect the circuit through which connection is made to said line in the second stage of its movement, and to close the circuit through which connection is made from said line to the others in the third stage of its movement, and mechanism at the substation of said line for controlling the movement of said switch.

2. In an automatic telephone exchange, the combination with a plurality of lines extending from substations to a central office, of a connecting circuit for connecting together any two of said lines, said connect-

- ing circuit consisting of a plurality of normally discontinuous links, electro-magnetic connecting switches for joining said links together, controlling switches for said connecting switches adapted to govern the actuation thereof, a circuit for said controlling switches and connecting switches, and an interrupter for said circuit at the substation of a line, said controlling switches being responsive to the number of interruptions of the circuit, and the connecting switches being responsive to the duration of the intervals between interruptions.
3. In an automatic telephone exchange, the combination with a plurality of lines extending from their respective substations to a central office, of controlling mechanism in the circuit of each line at its substation adapted to effect a sequence of variations in the electrical condition of the line, a connecting circuit at the central office comprising a plurality of links, electro-magnetically actuated connecting and controlling switches adapted to join said links into a continuous talking circuit, said controlling switches being responsive to the number of variations in the electrical condition of the circuit produced by the aforesaid substation mechanism, while the connecting switches are arranged to respond to the duration of the variations.
4. In an automatic telephone exchange, the combination with a plurality of lines extending from their respective substations to a central office, of link conductors at the central office for connecting for conversation any two of said lines, electro-magnetic switches controlling the continuity of said link conductors, an actuating circuit for said switches, said switches being responsive in part to the number of electrical variations in their actuating circuit and in part to the duration of said variations, and mechanism at the aforesaid substations adapted to produce such variations of the electrical condition of said actuating circuit.
5. In an automatic telephone exchange, the combination with a plurality of lines extending from their respective substations to a central office, of electro-magnetic connecting mechanism for said lines at the central office, an actuating circuit for the connecting mechanism, said mechanism being selectively responsive to the number and to the duration of electrical variations in said actuating circuit, and mechanism associated with one of said lines adapted to produce a predetermined sequence of variations in said actuating circuit following each other at predetermined intervals.
6. In an automatic telephone exchange, the combination with a plurality of lines extending from their respective substations to a central office, of electro-magnetic switches adapted to connect together any two of said lines, actuating circuits for said switches, said connecting switches being adapted to be selectively responsive to the duration of closure of said actuating circuits, electro-magnetic controlling switches associated one with each connecting switch and adapted to govern the closure of the actuating circuits of the associated connecting switches, an actuating circuit for said controlling switches, said controlling switches being responsive to the number of closures of said actuating circuit, and circuit interrupting mechanism associated with one of said lines at the substation thereof adapted to effect the interruption of said last mentioned actuating circuit a predetermined number of times at predetermined intervals.
7. In an automatic telephone exchange system, the combination with a calling line and a called line extending from their respective substations to a central office, of a connecting circuit adapted to join said lines together, an electrically actuated connecting switch in said circuit adapted to be selectively responsive to the duration of electric current flow therethrough, a normally open electrically actuated controlling switch interposed in said connecting circuit between said connecting switch and the calling line, and adapted to be selectively responsive to the number of variations in current flow therethrough, an energizing circuit for said switches, and circuit controlling mechanism at the substation of the calling line adapted to effect a predetermined number of variations in the current flow in said actuating circuit of a predetermined duration.
8. In an automatic telephone exchange, the combination with a metallic circuit line extending from a substation to a central office and means for producing a flow of current therein, of another line normally connected therewith at the central office, an electro-magnetic switch controlling the connection between said lines, said switch being adapted to interrupt the aforesaid connection upon the second of two consecutive impulses of current flowing over said metallic circuit, and mechanism at the substation for effecting consecutive interruptions of the circuit to produce current impulses therein.
9. In an automatic telephone exchange, the combination with a metallic circuit line extending from a plurality of substations to a central office, of signal apparatus at the substations adapted for selective operation, telephone apparatus and circuit interrupting apparatus included in bridges between the limbs of the line at the various substations, said line being free of ground connections at its substations, selective signal transmitting apparatus adapted to be associated with said line at the central office, selecting and connecting apparatus at the

- interrupting apparatus and adapted to connect said line with other lines, a control circuit for setting said selective signal transmitting apparatus and selecting and connecting apparatus, said circuit including the calling line conductors in series. 6
10. In an automatic telephone exchange, the combination with a line extending from a substation to a central office, a plurality of lines with which said line may be connected at the central office, an automatic switch for selecting any particular one of said lines and connecting the first mentioned line thereto, said switch having a movable member upon which said first mentioned line terminates and a plurality of fixed members whereon said other lines terminate, constantly and uniformly moving mechanism associated with said movable members, electro-magnetic mechanism adapted to bring said moving mechanism into engagement with said member, an actuating circuit for said electro-magnetic mechanism and a device at the substation adapted to control said actuating circuit, said device being adapted to close said circuit for predetermined intervals of time, whereby the extent of movement of the aforesaid movable switch member may be determined and any particular line selected. 10
11. In an automatic telephone exchange, the combination with a plurality of lines extending from substations to a central office, of a series of electrically actuated selecting switches for completing connection between any two of said lines, electrically actuated controlling switches associated with said selecting and connecting switches, said controlling switches being selectively responsive to the number of variations of current flow through their actuating coils, and the selecting switches being selectively responsive to the duration of current flow therethrough, actuating circuits for said switches, and a controlling device for determining the number and duration of current variations in said actuating circuit, whereby selective connection between the lines is effected. 15
12. In a switch for an automatic telephone exchange, the combination with a movable switch member and a plurality of fixed switch members, of constantly and uniformly moving mechanism associated with said movable member, electro-magnetic mechanism adapted to bring said moving mechanism into engagement with said movable member, an actuating circuit for said electro-magnetic mechanism, a contact of said switch normally completing said actuating circuit said contact being adapted to be opened when the switch is moved, and an alternative branch of said actuating circuit extending to the movable member of said switch, and a switch contact closed by said electro-magnetic mechanism when energized, controlling said alternative branch. 15
13. Connecting mechanism for an automatic telephone exchange, comprising a plurality of selecting switches, an electrically actuated controlling switch associated with each of said selecting switches, an actuating circuit for said switches, and means in said circuit for producing a predetermined number of variations in the current flow therein of 70 a predetermined duration, said selecting switches being responsive to the duration while the controlling switches are responsive to the number of variations of the current. 75
14. Connecting mechanism for an automatic telephone exchange, comprising a selecting switch, an electrically actuated controlling switch therefor, an actuating circuit for said controlling switch including a source of current, and means for producing a predetermined number of variations in the current flowing in said circuit of a predetermined duration, said controlling switch being selectively responsive to the number of said current variations, and 80 said selecting switch being selectively responsive to the duration of such variations. 85
15. Connecting mechanism for an automatic telephone exchange, comprising a plurality of selecting switches, an electrically actuated controlling switch associated with each selecting switch, an actuating circuit for said controlling switches, and means for producing current having peculiar characteristics in said actuating circuit, said controlling switches being selectively responsive to certain characteristics of said current, and said selecting switch being selectively responsive to other characteristics thereof. 95
16. Connecting mechanism for an automatic telephone exchange, comprising a selecting switch, mechanism for moving the same to effect selection, a calling line an electrically actuated controlling switch associated with said selecting switch, an actuating circuit including said calling line conductors in series for said controlling switch, a switch at the substation for closing said circuit, and means made active in the initial movement of said controlling switch to bring said selecting switch into operative relation with said moving mechanism. 100
17. Connecting mechanism for an automatic telephone exchange, comprising a selecting switch, mechanism for moving the same to effect selection, an electrically actuated controlling switch associated with said selecting switch, a calling switch, an actuating circuit for said controlling switch including the calling line conductors in series, means for producing current variations in said actuating circuit, means made active in the initial movement of said controlling switch to bring said selecting switch into 110
18. Connecting mechanism for an automatic telephone exchange, comprising a selecting switch, mechanism for moving the same to effect selection, an electrically actuated controlling switch associated with said selecting switch, a calling switch, an actuating circuit for said controlling switch including the calling line conductors in series, means for producing current variations in said actuating circuit, means made active in the initial movement of said controlling switch to bring said selecting switch into 115
19. Connecting mechanism for an automatic telephone exchange, comprising a selecting switch, mechanism for moving the same to effect selection, an electrically actuated controlling switch associated with said selecting switch, a calling switch, an actuating circuit for said controlling switch including the calling line conductors in series, means for producing current variations in said actuating circuit, means made active in the initial movement of said controlling switch to bring said selecting switch into 120
20. Connecting mechanism for an automatic telephone exchange, comprising a selecting switch, mechanism for moving the same to effect selection, an electrically actuated controlling switch associated with said selecting switch, a calling switch, an actuating circuit for said controlling switch including the calling line conductors in series, means for producing current variations in said actuating circuit, means made active in the initial movement of said controlling switch to bring said selecting switch into 125
21. Connecting mechanism for an automatic telephone exchange, comprising a selecting switch, mechanism for moving the same to effect selection, an electrically actuated controlling switch associated with said selecting switch, a calling switch, an actuating circuit for said controlling switch including the calling line conductors in series, means for producing current variations in said actuating circuit, means made active in the initial movement of said controlling switch to bring said selecting switch into 130

operative relation with said moving mechanism, and means actuated upon a subsequent movement of said controlling switch adapted to throw said selecting switch and its 5 moving means out of operative relation.

18. Connecting mechanism for an automatic telephone exchange, comprising a plurality of selecting switches, mechanism for moving said switches to effect selection, 10 electrically actuated controlling mechanism associated with each switch, an actuating circuit for said controlling mechanism, a device included in said actuating circuit for producing variations of current flow therein, each of said controlling mechanisms being responsive to certain of said variations and not responsive to others, means made operative in the initial movement of each 15 of said mechanisms for throwing its associated selecting switch into operative relation with the aforesaid moving means, and mechanism made operative in the subsequent movement of each of said mechanisms for throwing said selecting switch and its moving means out of operative relation, and extending said actuating circuit to another controlling mechanism.

19. Connecting mechanism for an automatic telephone exchange, comprising a selecting switch having stationary terminals and a movable terminal, said movable terminal being adapted for movement in two directions with respect to said stationary terminals, constantly moving means associated with said switch for producing said movements, electrically actuated mechanism adapted to throw said movable member into engagement with said means for producing one movement, other electrically actuated 35 mechanism adapted to throw said movable member into engagement with said means to produce the other movement and means for energizing either of said electrically actuated mechanisms.

40 20. Connecting apparatus for an automatic telephone exchange, comprising a selecting switch having stationary contact members and a movable contact member, said movable member being arranged to have a horizontal movement and a vertical movement, constantly moving means associated with said switch, and adapted to be thrown into engagement with said movable member to produce either the horizontal or 45 the vertical movement thereof, electro-magnetic coupling devices, one for controlling the horizontal and the other for controlling the vertical movement of said movable member, and means for actuating either of said coupling devices.

50 21. Connecting apparatus for an automatic telephone exchange, comprising a selecting switch having stationary contact members and a movable contact member, said movable member being arranged to have

a horizontal movement and a vertical movement, constantly moving means associated with said switch, and adapted to be thrown into engagement with said movable member to produce either the horizontal or the vertical movement thereof, electro-magnetic coupling devices, one for controlling the horizontal and the other for controlling the vertical movement of said movable member, 55 an actuating circuit for each of said coupling devices, a controlling switch associated with said selecting switch, and contacts thereof adapted to control said actuating circuits.

22. Connecting apparatus for an automatic telephone exchange, comprising a selecting switch having stationary contact members and a movable contact member, said movable member being arranged to have a horizontal movement and a vertical movement, constantly moving means associated with said switch, and adapted to be thrown into engagement with said movable member to produce either the horizontal or the vertical movement thereof, electro-magnetic coupling devices, one for controlling the horizontal and the other for controlling the vertical movement of said movable member, an actuating circuit for each of said devices, a controlling switch associated with said selecting switch, and contacts of said controlling switch included in said actuating circuits, said controlling switch being adapted in its movement first to close the circuit serving to bring about the vertical movement of the movable member of said selecting switch, then to open this circuit and close the circuit for effecting the horizontal movement of said member, and finally to open said last mentioned circuit.

23. A selecting switch for an automatic telephone exchange, comprising stationary contact members and a movable contact member, continuously operating means associated, but normally out of engagement, with said movable member, electrically actuated mechanism for bringing the same into engagement with said member, an actuating circuit for said electrically actuated mechanism, and a circuit changing device in said actuating circuit adapted to determine the duration of actuation of said mechanism, whereby the extent of movement of said movable member may be predetermined.

24. A selecting switch for an automatic telephone exchange, comprising stationary and movable contact members, said movable contact member being arranged to have a horizontal and a vertical movement, constantly and uniformly moving means associated, but normally out of engagement, with said movable member, electrically actuated mechanism for effecting the engagement of said means with said member for

producing its vertical movement, other electrically actuated mechanism for bringing about an engagement to effect the horizontal movement of said member, an actuating circuit for said vertical movement controlling mechanism, a circuit controlling switch in said circuit, and means for predetermining the time interval of the operation of said switch, whereby the extent of vertical movement of said member may be predetermined.

25. In an automatic telephone exchange, the combination with a line extending from a substation to a central office, of connecting apparatus for the line at the central office, said apparatus comprising a selecting switch having stationary and movable contact members, the movable member being arranged for vertical and horizontal movement, constantly moving means associated with said movable member but normally out of engagement therewith, an electro-magnet for causing engagement of said means with said member to effect its vertical movement, another magnet for causing engagement to effect the horizontal movement of said member, controlling circuits for said magnets, contacts associated with said switch for controlling the actuating circuit of the horizontal movement controlling magnet, and a switch at the substation adapted to control the circuit of the vertical movement controlling magnet.

26. In an automatic telephone exchange, the combination with a line extending from a substation to a central office, and means for producing current flow therein, of a circuit changing device at the substation adapted to produce a series of variations of current flow of predetermined duration, variable at will, and a series of electrically actuated connecting switch mechanisms at the central office, each of said mechanisms being arranged to have its movement started by one of the variations of current flow, and to have the extent of its movement determined by the duration of said variation.

27. In an automatic exchange, the combination with a line extending for a substation to a central office, and means for producing current flow therein, of a circuit changing device at the substation adapted to produce a series of variations in said current flow, each variation having a predetermined duration variable at will, and a series of electrically actuated connecting switches associated with the line at the central office, each of said connecting switches being arranged to have two movements of selection, means responsive to a variation of current flow in the circuit for starting one of said movements, means responsive to the duration of said variation for determining the extent of said movement and starting the second movement of said switch, and means responsive to the next variation for starting

the first movement of the succeeding switch.

28. In an automatic telephone exchange, the combination with a line extending from a substation to a central office, and means for producing current flow therein, of a circuit changing device at the substation adapted to produce a series of interruptions in said circuit, the intervals between said interruptions being of a predetermined length variable at will, a series of electro-magnetically actuated switches associated with the line at the central office, and a controlling switch associated with each of the aforesaid switches, each of said controlling switches responding selectively to certain of said circuit interruptions produced by the substation circuit changing device and, in its operation, effecting the actuation of its associated switch, and means for rendering the extent of actuation of said switch proportionate to the predetermined interval between the interruptions to which the controlling switch is responsive.

29. In an automatic telephone exchange, the combination with a line extending from a substation provided with a circuit interrupter to the central office, of a plurality of trunks with which said line is adapted to be connected at the central office, a switch for controlling the connection of the line with said trunks, said switch having a movable member upon which said line terminates, and stationary members upon which said trunks terminate, means for moving said movable member to bring it into operative relation consecutively with each of said trunk terminal members, electro-magnetic actuating means for the movable member of said switch, an actuating circuit therefor, said actuating circuit being adapted to be completed to cause the movement of said member by means of the aforesaid substation interrupter, mechanism actuated in the initial movement of said switch for interrupting said circuit and completing it through the trunks with which said member contacts in its movements, and means adapted to interrupt said circuit to stop the movement of said movable member when the same comes in contact with the terminal of an idle trunk.

30. In an automatic telephone exchange, the combination with a called line extending from a plurality of substations to a central office, of a signal adapted for selective operation at each of said substations, circuits at the central office adapted to supply signal current for the selective actuation of said substation signals, a calling line, and a switch controlled over the calling line conductors in series for effecting the connecting of any of said circuits to the line to actuate the signal at a particular substation.

31. In an automatic telephone exchange, the combination with a metallic circuit line extending from a plurality of substations to

a central office, of a signal adapted for selective operation connected in a bridge of said circuit at each of said substations, a source of signaling current at the central office 65
 5 adapted to supply currents having different characteristics for the selective operation of said substation signals, a switch for applying to the line, any one of said currents, electrically actuated mechanism for selectively 70
 10 operating said switch, a calling line, and a control circuit for said mechanism including the calling line conductors in series. 75

32. In an automatic telephone exchange, the combination with a line extending from 15 a plurality of substations to a central office, of a signal connected with the line at each of said substations, circuits at the central office for supplying signaling currents of different characteristics for the signaling 20 of any particular substation, a switch adapted to be moved to connect any of said circuits to the line, constantly operating mechanism for moving said switch, an electrically actuated device for bringing said 25 mechanism into engagement with said switch, an actuating circuit for said device, and switch contacts in said circuit adapted to close the same for any predetermined length of time, whereby the extent of movement of said switch is controlled to connect 30 any desired signaling circuit to the line.

33. In an automatic telephone exchange, the combination with a line extending from a plurality of substations to a central office, of a signal adapted for selective operation at each of said substations, an automatic ringing key at the central office adapted to apply ringing current to the line, a source of ringing currents having different 35 characteristics, an electrically actuated selective switch for applying current having a particular characteristic to the ringing key, a calling line, and a control circuit for 40 said switch including the calling line conductors in series.

34. In an automatic telephone exchange, the combination with a line extending from a substation to a central office, of a signal at the substation, a source of signaling current at the central office, a ringing key for applying said source of signaling current to the line, electrically operated mechanism adapted to actuate said ringing key a predetermined number of times, a calling line, 50 means associated therewith for starting the operation of said mechanism, and means controlled by said mechanism for terminating its operation.

35. In an automatic telephone exchange, 60 the combination with a line extending from a substation to a central office, of a signal connected with the line at the substation, a source of signaling current at the central office, a ringing key for applying said sig-

naling current to the line, electrically actuated mechanism for operating said ringing key, a calling line, means associated therewith for setting said electrically-actuated ringing mechanism in operation, a switch associated with said mechanism arranged to be actuated after the ringing key has been operated a predetermined number of times, a source of current having peculiar characteristics, a calling line, and a circuit for applying said peculiar current to the 75 calling line controlled by the aforesaid switch.

36. In an automatic telephone exchange, the combination with a line extending from a substation to a central office, of a signal connected with the line at the substation, a source of signaling current at the central office, a ringing key for applying said signaling current to the line, electrically actuated mechanism for operating said ringing key, a calling line, means associated therewith for setting said electrically-actuated ringing mechanism in operation, a switch associated with said mechanism arranged to be actuated after the ringing key has been 80 operated a predetermined number of times, a source of current having peculiar characteristics, and a circuit adapted to apply said current to the calling line and at the same time to interrupt the operation of said ringing mechanism controlled in the aforesaid switch associated with said ringing mechanism. 90

37. In an automatic telephone exchange, the combination with a calling line and a called line, and a telephone switch at the substation of the calling line, of a source of ringing current, electrically actuated mechanism for applying the same to the called line a predetermined number of times, a source of current having peculiar characteristics, a switch associated with the aforesaid ringing mechanism for applying said peculiar current to the calling line after 100 ringing current has been applied to the called line a predetermined number of times, and electro-magnetic mechanism responsive to the telephone switch at the substation of the calling line for maintaining the application of the peculiar current thereto. 105

38. In an automatic telephone exchange, the combination with a line extending from a substation to a central office, of means for producing current flow in said line, a device at the substation for producing a predetermined number of variations in the current flow, said variations being of a predetermined duration variable at will, and electrically actuated connecting mechanism 110 for said line at the central office comprising a selecting switch responsive to the duration of variations of current in the line, and a switch adapted to complete connection be- 115

tween the line and said selecting switch, said switch being responsive to the number of variations of current in the line.

39. In an automatic telephone exchange, 6 the combination with a calling line and a plurality of lines with which said calling line is adapted to be connected, of means for changing the electrical condition of any of said lines when in use, a connecting switch 10 for completing connection between the calling line and any one of said other lines, a source of ringing current, electrically actuated mechanism for applying said current to the called line for a predetermined 15 length of time, switch mechanism operated by said ringing mechanism at the end of said predetermined length of time, a source of current, of peculiar characteristics, a switch adapted to apply said 20 peculiar current to the calling line, and means responsive to the altered electrical condition of the called line in case the same is busy, and to the aforesaid switch mechanism operated by the ringing mechanism, 25 for actuating said switch.

40. In an automatic telephone exchange, the combination with a calling line and a called line extending from substations to a central office, of a connecting circuit for 30 said lines at the central office, a connecting switch included in said circuit, a control circuit therefor including the calling line conductors in series, said switch comprising a number of stationary terminals to one of 35 which said called line is connected, and a movable member to which said calling line is connected, said movable member being adapted to have two movements, electrically controlled mechanism for effecting one 40 movement of said member, electrically controlled mechanism for effecting the other movement of said member, a plurality of circuits for supplying ringing current of different characteristics, an electrically actuated 45 selecting switch for selecting a particular one of said circuits, an electrically actuated ringing key for applying current thus selected to the called line, an electrically actuated controlling switch, means for controlling the same located at a substation of 50 the calling line, and actuating circuits for the actuating mechanism of said connecting switch, ringing current selecting switch and ringing key, controlled in contacts of said 55 controlling switch.

41. In an automatic telephone exchange, a telephone line, switch mechanism comprising an electrically actuated connecting switch, a calling line, a control circuit for 60 said connecting switch including the calling line conductors in series, an electrically actuated switch for selecting ringing current of peculiar characteristics, an electrically actuated key for applying to a line the ringing current thus selected, an electrically actu-

ated controlling switch, circuit changing mechanism for governing the operation of the same, and actuating circuits for the aforesaid connecting switch selecting switch and ringing key controlled in contacts of 70 said controlling switch.

42. In an automatic telephone exchange, the combination with a calling line and a called line extending from their respective substations to a central office, of a connecting circuit for said lines at the central office, a connecting switch included in said circuit, said switch comprising a number of stationary terminals to one of which said called line is connected, and a movable member to which said calling line is connected, said movable member being adapted to have two movements, electrically controlled mechanism for effecting one movement of said member, an electrically controlled mechanism for effecting the other movement of said member, a plurality of circuits for supplying ringing current of different characteristics, an electrically actuated selecting switch for selecting a particular one of said circuits, an electrically actuated ringing key for applying current thus selected to the called line, an electrically actuated controlling switch, control circuits for said connecting switch and controlling switch including the conductors of the calling line in series, and actuating circuits for the actuating mechanism of said connecting switch, ringing current selecting switch and ringing key, controlled in contacts of said controlling switch, and other switch contacts of said controlling switch adapted to complete circuit between the calling and the called lines in the last movement of said controlling switch.

43. The combination with a calling line and a called line extending from their respective substations to a central office, of an electric magnet connected with the calling line at the central office, switch mechanism actuated by the magnet, a telephone and a circuit changing device associated with the calling line at the substation thereof, means associated with the called line for altering its electrical condition when in use, a magnet responsive to the altered electrical condition of said line, said magnet being arranged in inductive relation to said first mentioned magnet, and a source of varying electrical current completed through the winding of the last mentioned magnet by its response, whereby varying current is caused to flow by induction through the telephone associated with the calling line when the called line is found busy.

44. The combination with a telephone line circuit, of transmitter mechanism adapted to produce a succession of electrical changes therein at predetermined intervals of varying duration, a controller switch responsive to the number of such changes, a selector

130

switch, and means governed by said controller switch and operated during the interval between successive responses thereof for advancing said selector switch.

45. The combination with a telephone line circuit, of transmitter mechanism adapted to produce a succession of changes in the electrical condition thereof at predetermined intervals of varying duration, an electromagnetic step-by-step controller switch adapted in response to successive changes to advance in corresponding steps, a selector switch, and means brought into action by a given step of said controller switch and thrown out of action by a succeeding step thereof for advancing said selector switch; whereby selection is made according to the duration of the interval between the successive electrical changes produced by said transmitter mechanism.

46. The combination with a telephone line circuit, of means for establishing a definite succession of electrical changes therein at predetermined intervals of varying duration, a step-by-step controller switch responsive to the number of said electrical changes, a selector switch, electromagnetic operating mechanism for advancing said selector switch, and a local circuit for said electromagnetic operating mechanism closed by said controller switch in a given position of advance thereof, whereby the advance of the selector switch is proportional to the length of time said controller switch remains in a given position of its advance.

47. The combination with a metallic circuit, transmitter mechanism adapted to produce a succession of electrical changes in said circuit at different intervals, a series of selector switches by which said metallic circuit is successively extended, means responsive to the number of electrical changes for bringing the different selector switches successively under the control of said transmitter mechanism, and means for advancing each selector switch to an extent proportional to a corresponding interval between two electrical changes produced by said transmitter mechanism.

48. In an automatic telephone exchange, the combination with a selecting switch having two movements, an electromagnet for controlling each movement, and an electromagnet for retaining the switch in the position to which it is moved, a controlling circuit for said electromagnets, an interrupter in said circuit adapted to produce three momentary interruptions, and means for advancing said selecting switch through its first movement in proportion to the interval between the first two interruptions, and means for advancing said selecting switch through its second movement in proportion to the interval between the second and third interruptions; said retaining electromagnet

being unresponsive to said momentary interruptions.

49. The combination with a two-wire telephone line circuit, of a step-by-step controller switch having an operating electromagnet connected with a source of current in a bridge of the line, a transmitter switch adapted to produce a succession of momentary interruptions in the line circuit at predetermined intervals of definite but variable duration, a selector switch, a continuously acting motor mechanism for advancing said selector switch, an electromagnet governing the advance of said switch by said motor mechanism, and a local circuit for said electromagnet completed at a contact of said controller switch closed at a given step in the advance thereof, said local circuit being broken at a succeeding step of said controller switch, substantially as set forth. 85

50. In an automatic telephone exchange, a selectively operated connector apparatus comprising an automatic controller switch adapted to advance step by step under the influence of successive current impulses, and a selector switch having different movements, electromagnets respectively governing the different movements of said selector switch, operating mechanism controlled by each magnet for continuously advancing said selector switch in its corresponding movement during the excitation of each magnet, and local circuits for the respective magnets arranged to be closed in rotation by the successive steps of said controller switch, substantially as set forth. 90

51. In an automatic telephone exchange, the combination with calling lines, poly-station called lines and a selectively operated final connector adapted to extend a calling circuit into connection with a called line, of a plurality of sources of signaling current differing in character, for selectively signaling a called station, an auxiliary step-by-step selecting switch, controlling circuits including the calling line conductors in series for actuating said connector to select the called line and for actuating said auxiliary switch to select a particular one of said sources of calling current, substantially as set forth. 105

52. In an automatic telephone exchange, the combination with a final connector switch, of a step-by-step controller switch responsive to selecting impulses, local circuits including different operating magnets of said connector switch, an auxiliary calling-current selector, a local operating circuit therefor, a calling switch for applying the selected calling current, and a local circuit for said calling switch, said various local circuits being closed in rotation by said controller switch at successive steps in its advance. 110

53. In an automatic telephone exchange,

- the combination with a selectively-operated final connector switch for extending a calling circuit into connection with a called line, of a step-by-step auxiliary controller 5 responsive to successive selecting impulses, local operating circuits closed in rotation by successive steps of said auxiliary controller, governing the different selecting movements of said connector switch, a number 10 of sources of calling current of differing character, an auxiliary calling-current selector for selecting a given source of calling current, a local circuit for said calling-current selector closed by said auxiliary controller after the selecting movements of 15 said connector switches, a calling switch for applying the selected calling current to the line, an electromagnet for operating said calling switch, and a local circuit for said calling magnet closed by the auxiliary controller 20 at a succeeding step of its advance.
54. In a telephone exchange system, the combination with a selecting switch, motor mechanism therefor and a controlling circuit 25 for said mechanism, of means for producing a flow of current in said controlling circuit, means for producing a momentary interruption of current in said circuit, said mechanism being rendered responsive upon the 30 closure of said interruption to advance the selecting switch, and means for producing a second momentary interruption of current in said circuit, said mechanism being rendered responsive upon the occurrence of 35 said second interruption to stop the movement of the selecting switch.
55. In a telephone exchange system, the combination with an electro-responsive switch, and a controlling circuit therefor, 40 of a branch connection to said circuit controlled by said switch, and means for producing successive current variations in said circuit, said switch being adapted to respond upon the second of two consecutive current variations to interrupt the said branch connection.
56. In a telephone exchange system, the combination with an electro-responsive switch, a telephone line circuit, and a switch 45 for closing the line circuit of a branch connection to said line circuit leading to other switches, sending mechanism for producing successive current variations in said line circuit, said electro-responsive switch being adapted to respond upon the second of two consecutive current variations to interrupt the said branch connection.
57. In a telephone system, the combination with an electro-responsive switch and a controlling circuit therefor, of a normally 50 closed branch connection to said circuit, a busy test conductor associated with said controlling circuit, means for producing successive current variations in said circuit, said switch being adapted upon the first 55
- variation in current in the controlling circuit to close said busy test conductor and upon the second variation therein to open the said branch connection.
58. In a telephone exchange system, the 70 combination with an electro-responsive switch and a controlling circuit therefor, of a branch conductor normally connected to said circuit, a normally open extension of said circuit, a busy test conductor associated with said controlling circuit, means for producing successive current variations in said circuit, said switch being adapted in successive stages under the control of successive variations of said current first to 75 close the busy test conductor, second to open the normally closed branch conductor, and third to close the normally open extension of said circuit.
59. In a telephone exchange system, the 80 combination with subscribers' lines having terminals and a connecting circuit for said lines, of a source of current of peculiar characteristics, a switch adapted to apply 85 said current to the connecting circuit, means for altering the electrical condition of said terminals when the lines thereof are busy, an automatic ringing mechanism, and means responsive to the altered electrical condition of the terminals of the busy line and also to said automatic ringing mechanism 90 after a predetermined time for actuating 95 said switch.
60. In a telephone exchange system, the combination with subscribers' lines and a connecting circuit therefor, of an electromagnet connected to said circuit, means associated with each of said lines for altering its electrical condition when in use, a magnet associated with said connecting circuit arranged in inductive relation to said first mentioned magnet, a source of varying current adapted upon test being made of a busy line to flow through the winding of the last mentioned magnet, whereby varying current is caused to flow in the connecting circuit by induction between said magnets. 100
61. In an automatic telephone exchange system, the combination with a metallic line circuit and a plurality of substations connected thereto, of signal apparatus at the substations adapted for selective operation, telephone apparatus and circuit interrupting apparatus included in bridges between the limbs of the line at the various substations, selective signal transmitting apparatus adapted to be associated with said line at the central office and automatic selectors at the central office adapted to respond to 105 said substation interrupting apparatus. 115
62. In a telephone exchange system, the combination with a metallic circuit line extending from a plurality of substations to a central office, of a signal adapted for selective operation connected in a bridge of 120 125 130

- said circuit at each of said substations, a source of signaling current at the central office adapted to supply currents having different characteristics for the selective operation of said substation signals, a switch for applying to the line any one of said currents, electrically actuated mechanism for selectively operating said switch, a calling line, a controlling circuit including the calling line conductors in series and sending mechanism in said circuit adapted to control the selective operation of said switch to signal any particular substation. 5
63. In a telephone exchange system, the combination with a selector having motion in two planes, constantly moving mechanism and a motor magnet for connecting said mechanism to said selector to advance the same in both planes of a controlling circuit for said motor magnet, and sending mechanism in said circuit adapted to maintain said circuit continuously closed for predetermined periods of time, said motor magnet being adapted to respond to said current and the said selector being adapted to advance distances corresponding to said predetermined time periods. 10
64. Connecting mechanism for a telephone exchange comprising a selecting switch and a motor magnet therefor, of an actuating circuit for said motor magnet and means for producing a plurality of short interruptions of current in said actuating circuit, said motor magnet being responsive upon the closure of one of said interruptions to start the movement of said selecting switch, and upon the occurrence of the next succeeding interruption to stop the movement thereof. 15
65. In a telephone exchange system, the combination with a telephone line extending from a substation to a central office, of a connecting circuit at the central office, a switch for uniting said connecting circuit with said line, a party telephone line, an automatic switch for uniting said connecting circuit with said party line, and a second automatic switch mechanically independent of said first mentioned automatic switch for impressing selective ringing current on said party line. 20
66. The combination with a multi-station telephone line, of a calling line, an automatic connection switch for uniting said calling line with said multi-station line, a control circuit for settling said switch including the calling line conductors in series, and means automatically operable upon the closure of said connecting switch for selectively signaling the desired station of said line. 25
67. In a telephone exchange, the combination with a telephone line extending from a number of substations to a central office, of an automatic switch for making connection with such line at the central office, a calling line, a control circuit for setting said switch including the calling line conductors in series, mechanism operable upon the closure of said switch for automatically applying the proper current to said line to selectively signal the desired station thereon. 70
68. The combination with a telephone line extending from a substation to a central office, of a connecting circuit at the central office, a connection switch for uniting said connecting circuit with the line, a party telephone line extending from substations to a central office, automatic line switching mechanism adapted to unite said connecting circuit to said party line, means automatically operated when said switching mechanisms unites with the party line for selectively signaling the desired station thereon, and means automatically operated when the subscriber at said station responds for removing said ringing current from the line. 75
69. In a telephone exchange system, the combination with a telephone line extending from a substation to a central office, of link conductors at the central office, a connection switch for uniting said link conductors with the line, a party line extending from a number of substations to a central office, a connector carrying the terminals of such line, a contact carrying arm for said connector adapted to be connected with said link conductors, automatically operated mechanism for advancing the contact arm to the terminals of such party line, a control circuit for said mechanism including the conductors of said telephone line in series, and automatic means for impressing a selected ringing potential on said party line through said connector. 80
70. The combination with a multi-station telephone line, of a calling line, an automatic connection switch, a control circuit for said switch including the conductors of said calling line in series, and a ringing current selector individual to said connector also adapted to be set over said control circuit. 85
71. In an exchange system, the combination with a plurality of metallic line circuits extending from substations to a central office, of a plurality of line selectors at the central office, non-numerical automatic line switches for said lines for associating an idle line selector with the calling line, switch mechanism at each substation adapted to produce current variations in the line circuit, and means at the central office responsive to said variations adapted to cause a series of said selectors operating in succession to connect said metallic line circuit with another for telephonic communication. 90
72. In a telephone exchange system, the combination with a plurality of line circuits, each comprising two conductors extending 100
- 105
- 110
- 115
- 120
- 125

from a substation to a central office, of group and individual line selectors at the central office, non-numerical automatic line switches for said lines for associating an idle group 5 selector with the calling line, switch mechanism at each substation adapted to produce current variations in the line circuit thereof, and means at the central office responsive to said current variations to cause a series of 10 said selectors operating in succession to connect said line circuit with another for telephonic communication.

73. In a telephone exchange system, the combination with subscribers' line circuits, 15 each comprising two conductors extending from the substation thereof to a central office, of switch mechanism at each substation for producing current variations in the line circuit thereof, a series of selectors 20 at the central office, non-numerical automatic line switches for said lines for associating an idle selector with the calling line, said selectors operating in succession in response to said current variations and 25 adapted thereby to interconnect such line circuit with another for telephonic communication.

74. In a telephone exchange system, the combination with a plurality of metallic 30 line circuits, of means for producing current variations in said circuits, a group selector switch and a line connector switch, non-numerical automatic line switches for said lines for associating an idle group 35 selector with the calling line, said switches being adapted to operate in succession in response to such current variations to interconnect the said circuits for telephonic communication.

40 75. In a telephone exchange system, the combination with a plurality of subscribers' lines, each comprising the two conductors of a metallic circuit, of means for producing current variations in successive periods in 45 said circuit conductors, group selector switches and line connector switches associated with said lines, non-numerical automatic line switches for said lines for associating an idle group selector with the 50 calling line, said switches being adapted to operate one after another during such successive periods in response to said current variations to interconnect said line circuits for telephonic communication.

55 76. In a telephone exchange system comprising trunk lines extending between switchboards, the combination with means at the outgoing end of the trunk line for connecting a calling subscriber's line there- 60 to, means at the incoming end of the trunk line for connecting the trunk with a wanted subscriber's line, a control circuit for said means including the calling line conductors in series, said line serving more than one 65 subscriber's station, a plurality of generat-

ing devices, and automatic means individual to the trunk line for selecting and connecting the proper generator to operate the signaling devices at the desired station.

77. In a telephone exchange system, a 70 plurality of subscribers' lines including party lines terminating at different central offices, and trunk lines interconnecting the central offices, means for connecting said trunk lines with calling subscribers' lines, 75 means for connecting the trunk lines with wanted subscribers' lines, a control circuit for said last mentioned means including the calling line conductors in series, switching means for selectively ringing the bells at 80 any one of several stations of the same line, with separate transmitting means for selectively controlling the same through a trunk line when connected.

78. In a telephone exchange system, a 85 trunk line between exchanges for interconnecting subscribers' lines terminating at the different exchanges, a selective transmitter associated with the originating end of said trunk, selective ringing devices at the calling end of the trunk responsive to said transmitter, and a control circuit for said selective ringing devices including said transmitter and the conductors of said 90 trunk line in series.

79. In a telephone exchange system, means for trunk ringing over party lines comprising a plurality of harmonic generating devices at the calling end of a trunk, an automatic switching device for applying the same selectively to a called line when the trunk is connected thereto, an electromagnetic switch associated with the trunk and controlling said switching device, and an impulse transmitter for controlling said electromagnetic switch by a circuit including the trunk conductors in series. 100

80. In a telephone exchange system, trunk ringing means comprising a selective transmitter, a ringing selector responsive thereto at the B end of each trunk, and electro-mechanisms associated with the B end of the trunk for connecting the ringing generator to a called subscriber's line, and responsive to the act of the called subscriber for disconnecting said ringing generator. 110

81. In a telephone exchange system, trunk ringing means comprising an impulse transmitter associated with the A end of a trunk, a plurality of selective ringing generators at the B end of the trunk, with automatic switching means responsive to the transmitter at the A end of the line to select any one of said generators, a ringing device comprising an electromagnet and a 120 commutator for connecting the selected generator to the called line, and an electromagnet responsive to the act of the called subscriber adapted to control said ringing device. 125

82. In a telephone exchange system, the combination with a plurality of subscribers' line circuits each comprising two conductors without ground connections at the station thereof, of a switch mechanism at each substation adapted to cause current variations in a circuit including two line conductors thereof, a series of automatic switch mechanisms, non-numerical automatic line switches for said lines for associating an idle switch mechanism with the calling line, said switches operating in succession in response to said current variations and adapted thereby to connect said line conductors with the corresponding conductors of another line for telephonic communication.

83. In a telephone exchange system, the combination with a plurality of metallic line circuits free from operative grounds outside of the central office, of means for producing current variations in any one of said circuits, a plurality of automatic switches, non-numerical automatic line switches for said line circuits for associating an idle automatic switch therewith, said automatic switches adapted to operate in succession in response to such current variations to connect one of said metallic line circuits with another for telephonic communication.

84. In an automatic telephone exchange system a plurality of subscribers' stations and metallic circuit lines extending thence to a central office, automatic switching apparatus for interconnecting the lines at the central office, non-numerical automatic line switches for associating calling lines with said automatic switching apparatus, a source of current connected in the metallic circuit of a subscriber's line, means at the substation to make and break the said metallic circuit at will, the makes and the breaks being of varying but predetermined duration, and means at the central office responsive to such makes and breaks in the metallic circuit to actuate, control and release the automatic switching apparatus and also to ring the wanted subscriber, substantially as described.

85. In a telephone exchange system a plurality of subscribers' stations and metallic circuit lines extending therefrom to a central office, automatic switching apparatus having one or more actuating magnets and release magnets and a common source of current supply for the lines at the central office, non-numerical automatic line switches for associating calling lines with said automatic switching apparatus, a telephone at each substation adapted to be bridged across the metallic circuit and to derive current therefrom for talking purposes, and means at each substation to make and break the metallic circuit in accordance with any desired or necessary code signal, together with means at the central office responding to the makes

and breaks of the metallic circuit and adapted to actuate the automatic switching apparatus, to shift the control of the actuating means to that end as required, to ring the wanted subscriber, and finally to release and clear out the apparatus, substantially as described.

86. In a telephone exchange system a plurality of subscribers' stations and metallic circuit lines extending therefrom to a central office, automatic switching apparatus having one or more actuating magnets and release magnets and a common source of current supply for the lines at the central office, non-numerical automatic line switches for associating calling lines with said automatic switching apparatus, a telephone at each substation adapted to be bridged across the metallic circuit and to derive current therefrom for talking purposes, and means at each substation to make and break the metallic circuit in accordance with any desired or necessary code signal, together with means associated with each line at the central office responding to the makes and breaks of the metallic circuit and adapted to actuate the automatic switching apparatus, to shift the control of the actuating means to that end as required, to ring the wanted subscriber, and finally to release and clear out the apparatus, substantially as described.

87. In an automatic telephone exchange system, subscribers' two-wire lines with substation controlling apparatus, and central office automatic switches, each switch comprising an actuating member or spindle, contact devices moved thereby to effect the desired connection, and controlling devices for said switch comprising magnets and relays only, separate local circuits for the several magnets, adapted to be selectively energized, to produce the proper movements of the contact devices, a switch circuit constituting a continuation of the subscriber's line circuit, and relays responsive to current in said circuit and adapted to vary the connections in the local circuits so as to selectively shift the control thereof as and for the purpose stated, and non-numerical automatic line switches for associating calling lines with said automatic switches.

88. In an automatic telephone exchange system, the combination of a calling telephone line, a called telephone line, a series of automatic switches for extending connection from the calling line to the called line, a non-numerical automatic line switch for said calling line for associating an idle automatic switch therewith, a plurality of line circuits by which said switches are successively controlled, each said line circuit including the two sides of the calling line in series, and means for supplying current over the telephone lines to operate said switches, and for talking purposes also.

89. In a telephone exchange system, the combination of a calling telephone line, a called telephone line, a series of automatic switches for extending connection from the calling line to the called line, a non-numerical automatic line switch for said calling line for associating an idle automatic switch therewith, means for opening the calling line to release said switches, means for releasing said switches by the opening of said line, and means for supplying current over the telephone lines to operate said switches, and for talking purposes also.

90. In a telephone exchange system, the combination of a subscriber's telephone line, an automatic switch, a non-numerical automatic line switch for said line for associating an idle automatic switch therewith, a rotatable calling device adapted by its backward rotation to intermittently close together the two sides of the telephone line, means in said automatic switch for responding to the intermittent closing of the line, means for restoring the automatic switch to normal position by opening the line, and means for supplying current over the subscriber's telephone line to operate said automatic switch, and for talking purposes also.

91. In a telephone exchange system, the combination of telephone lines, automatic connectors less in number than said telephone lines, selectors less in number than the telephone lines, subscribers' individual switches corresponding in number to the telephone lines, subscribers' devices for closing the lines to control said individual switches and selectors and connectors, line circuits by which the said individual switches and selectors and connectors are controlled, each line circuit including the two sides of a calling telephone line in series, means for releasing said individual switches and selectors and connectors by the opening of the calling line, and means for supplying current over the telephone lines to operate said connectors and selectors and individual switches, and for talking purposes also.

92. In a telephone system, the combination of a second selector, a connector provided with a line relay, said relay provided with an energizing circuit, means for automatically closing said circuit as soon as the selector seizes the connector, and means for supplying current over the subscribers' lines to operate said selector and connector, and for talking purposes also.

93. In a telephone system, the combination of a calling telephone line, a called telephone line, automatic switches for trunking the calling line into connection with the called line, a non-numerical automatic line switch for said calling line for associating an idle automatic switch therewith, means for opening the calling line to release or re-

store the said switches, the said switches provided with release mechanism responsive to the opening of the calling line to release the switches either before or after the called subscriber answers, and means for supplying current over the telephone lines to operate said switches, and for talking purposes also.

94. In a telephone system, the combination of telephone lines, trunk-lines, automatic self-contained trunk selectors for selecting idle trunk-lines, non-numerical automatic line switches for said lines for associating an idle trunk selector with the calling line, automatic self-contained connectors for completing connection with the called telephone lines, line circuits for controlling said selectors and connectors, said line circuits each including the two sides of a calling telephone line in series, and means for supplying current over the telephone lines to operate said selectors and connectors, and for talking purposes also.

95. In a telephone system, the combination of a plurality of switches each adapted for both vertical and rotary motion, telephone lines, non-numerical automatic line switches for said lines for associating an idle switch with the calling line, line circuits for successively controlling the said switches to extend connection from a calling line to a called line, said line circuits each including the two sides of the calling line in series, and means for supplying current over the telephone lines to operate said switches, and for talking purposes also.

96. In a telephone system, the combination of telephone lines, non-numerical individual switches for said lines, line circuits for controlling said switches, said line circuits each including the two sides of a telephone line in series, means directly responsive to the opening of a connected telephone line for restoring the individual switches of the calling and called lines to normal condition, and means for supplying current over the telephone lines to operate said switches, and for talking purposes also.

97. In a telephone system, the combination of a plurality of automatic switches, telephone lines, non-numerical automatic line switches for said lines for associating an idle automatic switch with the calling line, line circuits for successively controlling said switches to extend connection from a calling line to a called line, means for opening the lines when the subscribers hang up their telephones, means directly responsive to the opening of a connected telephone line for initiating the release of all switches between the lines of calling and called subscribers, and means for supplying current over the telephone lines to operate said switches, and for talking purposes also.

98. In a telephone system, the combina-

- tion of a non-numerical automatic switch, a telephone line leading to said switch, means for closing together the two sides of the line, locking means contingent upon the closure of the line for holding the said switch in an off-normal position, and means for supplying current over the telephone line to operate said switch, and for talking purposes also.
10. 99. In a telephone system, the combination of a subscriber's telephone line, trunk-lines, an automatic non-numerical trunking switch individual to the telephone line for selecting an idle trunk, means for closing together the two sides of the telephone line, locking means dependent upon the closure of the line circuit for holding the switch in an off-normal position, and means for supplying current over the subscriber's line to operate said switch, and for talking purposes also.
10. 100. In a telephone system, the combination of a plurality of switches, telephone lines, non-numerical automatic line switches for said lines for associating an idle switch with the calling line, line circuits for successively controlling said switches to extend connection from a calling line to a called line, said circuits each including the two sides of a calling telephone line in series, a subscriber's releasing device for each line, each of said switches being provided with a release mechanism directly responsive to any subscriber's releasing device, and means for supplying current over the telephone lines to operate said switches, and for talking purposes also.
10. 101. In a telephone system, the combination of trunk-lines, an automatic non-numerical trunking switch provided with trunk-selecting mechanism, and with releasing mechanism, a telephone line, a subscriber's releasing device for said telephone line, line circuits for controlling the operation of said switch, said circuits each including the two sides of the telephone line in series, the release mechanism of said switch being directly responsive to a subscriber's releasing device, and means for supplying current over the telephone line to operate said switch, and for talking purposes also.
10. 102. In a telephone system free from operating grounds at the substations thereof, the combination of telephone lines, automatic trunking and connecting switches, non-numerical automatic line switches for said lines for associating an idle one of said trunking switches with the calling line, line circuits by which a calling subscriber successively controls a plurality of said switches to extend connection to the called subscriber's line said circuits each including the two sides of a calling telephone line in series, subscribers' releasing devices for the telephone lines, means immediately responsive to said releasing devices for releasing or restoring said switches to normal condition, and means for supplying current over the telephone lines to operate said switches, and for talking purposes also.
103. In a telephone system free from operating grounds at the substations thereof, the combination of telephone lines, automatic switches non-numerical automatic line switches for said lines for associating an idle one of said automatic switches with the calling line, line circuits for successively controlling a plurality of said switches to extend connection to a called subscriber's line, said line circuits each including the two sides of a calling telephone line in series, each automatic switch provided with a switch shaft adapted for both vertical and rotary motion, means carried by the shaft of each switch for extending connection in the direction of the called subscriber, and means for supplying current over the telephone lines to operate said switches, and for talking purposes also.
104. In a telephone system, the combination of telephone lines, a plurality of connector switches less in number than said telephone lines, locking means dependent upon the use of said connector switches for connecting purposes to hold the same in an off-normal position, automatic means for restoring said connector switches when thrown into an off-normal position while idle, and means for supplying current over the telephone lines to operate said switches, and for talking purposes also.
105. In a telephone system, the combination of trunk-lines, a first-selector switch adapted to select idle trunk-lines, locking means dependent upon the use of said selector switch for connecting purposes to hold the same in an off-normal position, automatic means for restoring said first-selector when thrown into an off-normal position while idle, and means for supplying current over the subscribers' lines to operate said first-selector switch, and for talking purposes also.
106. In a telephone system, the combination of trunk-lines, a second-selector switch adapted to select idle trunk-lines, locking means dependent upon the use of said selector switch for connecting purposes to hold the same in an off-normal position, automatic means for restoring said second-selector when thrown into an off-normal position while idle, and means for supplying current over the subscribers' lines to operate said second-selector switch, and for talking purposes also.
107. In a telephone system, the combination of trunk-lines, a subscriber's individual switch adapted to select idle trunk-lines, locking means dependent upon the use of

said individual switch for connecting purposes to hold the same in an off-normal position, automatic means for restoring said individual switch when thrown into an off-normal position while idle, and means for supplying current over the subscribers' lines to operate said individual switch, and for talking purposes also.

108. In a telephone system, the combination of a calling substation and a called substation, a series of switches for trunking the calling station into connection with the called station, switch shafts for each of said switches, means whereby if the shaft of any switch in the series is released the switch to which said shaft belongs is released, and also all of the subsequent switches between the said released switch and the called subscriber, and means for supplying operating and talking current from the central station.

109. In a telephone system, the combination of a calling line and a called line, a series of switches for trunking the calling line into connection with the called line, a shaft for each of said switches, means whereby if any shaft is rotated to break the established circuit every switch in the series between said shaft and the called subscriber is automatically released, and means for supplying operating and talking current from the central station.

110. In an automatic common battery telephone system, the combination of a calling line and a called line, a series of switches for trunking the calling line into connection with the called line, a non-numerical automatic line switch for said calling line for associating an idle one of said switches therewith, means whereby the calling subscriber may break the connection and restore said switches by simply separating his line conductors, and means for supplying operating and talking current from the central station, substantially as set forth.

111. In a telephone system, the combination of a calling line and a called line, a series of switches for trunking the calling line into connection with the called line, a non-numerical automatic line switch for said calling line for associating an idle one of said switches therewith, means whereby the calling subscriber may release the switches, either before or after the called subscriber answers, by simply opening up his line, and means for supplying operating and talking current from the central station, substantially as set forth.

112. In a telephone system, a calling line, the combination of a series of automatic switches, a non-numerical automatic line switch for said line for associating an idle one of said automatic switches with the calling line, means for successively operating said switches, and then releasing the same

by controlling circuits including both sides of the calling line in series, and means for supplying operating and talking current from the central station.

113. In a telephone system, a calling line, a called line, a connector provided with an element having motion in one direction to select groups and in another direction to find the called line, a non-numerical automatic line switch for said calling line for associating an idle connector with the calling line, release mechanism for restoring the connector to normal position, and a single line relay operative to control the motions of said element in both directions and the release of said connector.

114. In a telephone system, a plurality of trunks, an automatic trunking switch provided with an element having vertical and rotary motion to find an idle trunk, a single line relay operative to control the vertical motion and start the rotary motion, a calling line, and a non-numerical automatic line switch for said line for associating an idle trunking switch therewith.

115. In a telephone system, a plurality of trunks, an automatic trunking switch provided with line wipers having vertical and rotary motion to find an idle trunk, a single line relay operative to control the vertical motion and start the rotary motion, a calling line, and a non-numerical automatic line switch for said line for associating an idle trunking switch therewith.

116. In a telephone system, a plurality of groups of lines including a called line, a connector provided with line wipers having vertical and rotary motion to find the group and the called line of the group, a single line relay operative to control the vertical and rotary motion, a calling line, and a non-numerical automatic line switch for said calling line.

117. In a telephone system, the combination with groups of lines including a called line, a connector provided with an element having vertical and rotary motion to find the group and then the called line of the group, release mechanism for restoring the connector to normal position, a calling line, a non-numerical automatic line switch for said line for associating an idle connector therewith, a single line relay operative to control the vertical and rotary motion and the release of said connector, and means for controlling said relay over a metallic line circuit.

118. In a telephone system, the combination of a plurality of trunks, an automatic trunking switch provided with an element having vertical and rotary motion to find an idle trunk, a calling line, a non-numerical automatic line switch for said line for associating an idle trunking switch therewith, a single line relay operative to control the

vertical motion and start the rotary motion, and means for controlling said relay over a metallic line circuit.

119. In a telephone system, the combination of a plurality of trunks, an automatic trunking switch provided with line wipers having vertical and rotary motion to find an idle trunk, a calling line, a non-numerical automatic line switch for said line 10 for associating an idle trunking switch therewith, a single line relay operative to control the vertical motion and start the rotary motion, and means for controlling said relay over a metallic line circuit.

120. In a telephone system, the combination with a group of lines including a called line, a connector provided with line wipers having vertical and rotary motion to find the group containing the called line and 20 then the called line in the group, a calling line, a non-numerical automatic line switch for said line, a single line relay operative to control the vertical and rotary motion of said connector, and means for controlling 25 said relay over a metallic line circuit.

121. An automatic telephone system including calling and called lines, first selectors, a non-numerical automatic line switch for said calling line for associating an idle 30 first selector therewith, second selectors, connectors, means for adjusting said first selectors by impulses over the metallic circuit conductors of the calling line in series, and means for adjusting the selected second selectors and connectors by repeating the calling line impulses at the first selectors.

122. A telephone exchange system comprising a two-conductor circuit, associated 40 automatic switch mechanism having waiting contacts divided into groups and a cooperating moving contact, a non-numerical automatic line switch for associating said circuit with said automatic switch mechanism, means outside of said mechanism for rendering some of said waiting contacts busy, means for advancing said moving contact to a desired group of waiting contacts in response to a variation of current transmitted 45 over said circuit, means for starting said moving contact in search of an idle contact in that group in response to another current variation transmitted over said circuit, and means for continuing the movement of said moving contact in such search and stopping it only when an idle waiting contact is reached.

123. A telephone exchange system comprising a telephone line extending from a central office to a distant point, a source of current in circuit with said line, manually controlled means at said distant point for interrupting the circuit of the line, other telephone lines, an electrically controlled switch at the central office for establishing connection between said line and said other

lines, active contacts for said switch constituting terminals for said line, passive contacts for said switch constituting terminals for said other lines, restoring means for said switch, a non-numerical automatic line 70 switch for associating said switch with said telephone line, means responsive to short making and breaking of the circuit of said line for causing a primary operation of said first switch, and means responsive after connection is established with a desired line whereby a long interruption of the circuit of said line will cause a secondary operation of said first switch. 75

124. A telephone exchange system comprising a two-conductor telephone circuit, associated automatic switch mechanism having waiting contacts divided into groups and a cooperating moving contact, means outside of said mechanism for rendering some 80 of said waiting contacts busy, means for advancing said moving contact to a desired group of waiting contacts in response to current variation transmitted over the two talking conductors of said circuit in series, 85 means for starting said moving contact in search of an idle contact in that group, means for continuing the movement of said moving contact in such search and stopping it only when an idle waiting contact is 90 reached, and a non-numerical automatic line switch for associating said telephone circuit with said automatic switch mechanism. 95

125. In a telephone system, the combination with group selectors and a connector switch, a calling line, a non-numerical automatic line switch for associating an idle group selector therewith, of stationary and movable contacts associated with said connector switch, means for controlling said 100 group selectors and connectors by interruptions in the calling subscriber's line circuit, busy back signaling apparatus, and means operable to automatically apply a busy signal to the calling subscriber when 105 the movable contacts of said connector switch engage the stationary contacts of a busy line. 110

126. The combination of a bank of trunks having terminals, means for selecting an idle terminal, a wiper adapted and operative to reach the selected terminal by one continuous movement, and a vertical and rotary motion switch for each trunk. 115

127. An automatic telephone system including a pair of telephone lines, a plurality of selective switches linking said lines together, a release circuit extending to a plurality of switches linking said lines, electromagnetic release mechanism for each 120 of said plurality of switches, and means for closing said circuit long prior to the time of release and thereafter maintaining it continually closed and for opening said circuit when release is desired to deener. 125 130

gize said mechanisms to cause restoration of their respective switches.

128. An automatic telephone system including a pair of telephone lines, a plurality of link circuits interconnecting said lines, a number of directly controlled selective switches included in the connection, said switches being first connected to the calling subscriber's line and then operated to extend the connection in the direction of the called subscriber's line, an electromagnet, one for each of said switches for use in restoring the same, said electromagnets being held energized while connection exists, switching means responsive to the opening of the metallic circuit of one of said telephone lines for deenergizing and restoring said electromagnets, and means responsive to any restoration of said electromagnets to restore the switches.

129. In an automatic telephone system including an electrically adjustable selective switch, another selective switch adapted for selection by said first mentioned switch, an electromagnet for said other switch for use in restoring the same, means for energizing said electromagnet as soon as said other switch is selected and thereafter continuously holding it energized, and switching means for deenergizing and restoring said electromagnet, and means whereby any restoration of said electromagnet will restore said other switch when disconnection is desired.

130. In a telephone exchange system, the combination of subscribers' telephone lines, automatic means for extending a connection from a calling telephone line to a called telephone line including a wiper having vertical and rotary motion, disconnecting or releasing means including a magnet energized during talking, and means for operating said disconnecting or releasing means by the opening of a subscriber's line and the consequent deenergizing of said magnet, without grounding the line.

131. In a telephone exchange system, the combination of subscribers' telephone lines, automatic means for extending connection from a calling telephone line to a called telephone line including a wiper having vertical and rotary motion, a non-numerical automatic line switch for said calling line for associating said automatic means therewith, disconnecting or releasing means adapted to be operated by the opening of a telephone line, and means by which a subscriber when through talking opens his line to thereby operate the said disconnecting or releasing means without grounding the line.

132. In a telephone system, a line, means for supplying ringing currents of different frequencies, a mechanism for selecting the different frequencies one at a time, and means for controlling said mechanism from

a station on said line over the two sides of the line in series.

133. In a telephone system, a line, means for supplying different kinds of signaling current, a mechanism for selecting the different kinds of current one at a time, and means for controlling said mechanism from a station on said line over the two sides of the line in series.

134. In a party line telephone system, the combination with a calling and a called line each having a plurality of connected stations, of connector switches and selective signaling mechanism cooperating therewith for connecting said lines and signaling any desired station on the called line, selector switches and a non-numerical trunking switch individual to the calling line for extending said line to one of said connectors, and a calling device at the calling station adapted to control the operation of said selector and connector switches by series of interruptions produced in the line circuit including the two sides of the calling line in series.

135. In a telephone system, a plurality of lines each having a plurality of connected substations, automatic switching mechanism at the exchange controllable over the two sides of a calling line in series for extending a connection to a called line, and selective signaling equipment at the exchange for signaling a wanted substation on a connected called line.

136. A telephone system including a telephone line, a plurality of substations on said line, signals at said stations responsive to ringing currents of different frequencies corresponding to the number of substations on said line, sources of ringing current of such frequencies, a directly controlled electrically operated switch for selectively connecting said sources to said line to operate said signals, and directly controlled switches structurally independent of said switch for interconnecting said lines.

137. A telephone system comprising a calling and a called subscriber's line, a link circuit for connecting said lines, means included in said link circuit for automatically applying ringing current to the said called subscriber's line, electromagnetic means responsive to a control exercised at the substation of the calling line for disassociating said calling line and said link circuit, and means controlled by said electromagnetic means for interrupting the application of ringing current to the called subscriber's line.

138. A telephone system comprising telephone lines, a link circuit for interconnecting said lines, means for intermittently applying ringing current to a called one of said lines, and means controlled at the substation of a calling one of said lines for dis-

associating his line from said link circuit and for interrupting such application of ringing current.

139. A telephone system comprising a pair of connected telephone lines, means for applying ringing current to one of said lines, means controlled at the substation of the other of said lines for disassociating said lines and for interrupting the application of ringing current to the first one of said lines.

140. A telephone system comprising a pair

of connected telephone lines, means for applying ringing current to one of said lines, means controlled at the substation of one of said lines for disassociating said lines, and means controlled at the substation of either of said lines for interrupting such application of ringing current.
